UNITED STATES PATENT OFFICE

BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY

LASTING MACHINE

Application filed July 15, 1929. Serial No. 378,336.

This invention relates to machines for use in the manufacture of shoes, and in many of its aspects has more particular reference to machines for lasting shoes. The invention is herein illustrated as applied to a machine organization of the same general character as that disclosed in Letters Patent No. 1,775,225, granted upon an earlier application of mine on September 9, 1930, especially adapted for use in the lasting of tennis shoes or the like in which the uppers are fastened to the insoles by cement, and important objects are to provide improvements in an organization of that character. It is to be understood, however, that in various novel and useful aspects the invention is not limited to machines of the particular type therein disclosed nor to machines for lasting tennis shoes.

One important object of the invention is to provide improved means for laying the margin of an upper over an insole and for pressing it upon the insole in the lasting operation, for example, as herein illustrated, in the lasting of the sides of a shoe between its toe and heel end portions. Machines of the illustrated type are provided with side-lasting mechanisms comprising flexible lasting straps and members or fingers arranged to act through the straps to lay the upper over the insole, these members being movable inwardly over the bottom of the shoe and also movable heightwise of the shoe to press the upper upon the insole. For purposes of this invention the machine herein shown is provided with automatic yieldable means which operates independently of the lasting straps to impart to the above-mentioned members upper-pressing movement toward the bottom face of the insole early in their inward movement over the shoe, with a progressive increase of the pressure thereafter in their further inward movement. This contributes to the production of a tightly lasted shoe with the margin of the upper pressed evenly and firmly upon the bottom face of the insole to which, in a shoe of the type illustrated, it adheres through the action of the cement. In addition to novel features involved in such a combination of lasting straps and

members or fingers acting through the straps in the manner described, features of novelty are also to be recognized in the disclosed combination of lasting fingers with their operating and controlling means.

55

The invention further provides a novel combination of upper-shaping or lasting means and means for clamping the upper against the last, such means being arranged in the machine herein shown to operate at the sides of the shoe between its toe and heel end portions. A special object thus in view is to guard against danger of distortion of uppers in the side-lasting operation when the uppers are not laced at the time of that operation, as is sometimes the case in the manufacture of tennis shoes. For the purpose in view, the illustrated machine is provided with devices which clamp against the sides of the last portions of the upper that are subject to strain in the operation of the side-lasting mechanisms at the shank portion of the shoe, these devices being arranged to engage the upper in locations spaced substantially from the bottom of the last to afford room for upwiping of the upper by the lasting straps. The clamping devices shown comprise thin spring-metal fingers arranged to be overlapped by portions of the lasting straps. Novelty is also to be recognized in the means for controlling the side-clamping devices. Machines of the type illustrated include in their organization heel-lasting mechanism mounted for positioning movement toward the heel end of the shoe prior to the starting of the power operation of the machine, and in the construction shown the side-clamping devices are controlled by the positioning movement of the heel-lasting mechanism so as to be swung yieldingly into operative position as that mechanism is moved to its operative position.

60

65

70

75

80

90

95

Other novel features are to be recognized in the heel-lasting means and portions of the machine that are closely associated therewith. In accordance with one feature, the construction is such that the above-mentioned positioning movement of the heel-lasting mechanism, effected by automatic means under control of the operator, is a rectilinear move-

100

ment, the construction shown comprising a slide that is thus movable toward and from the shoe. It is a further characteristic of machines of the illustrated type that the heel-lasting wipers are controlled by a positioning device which moves them heightwise of each shoe against the resistance of springs to a position determined by a member engaging the bottom of the shoe, with provision for tipping of the wipers lengthwise and laterally of the shoe into proper relation to the shoe bottom; and the invention provides improvements in the means for thus controlling the wipers, the construction shown comprising members for engaging the wiper mechanism in three separate locations to effect its positioning movement, with provision for adjustment of one of the members to vary the position of the wipers in respect to inclination lengthwise of the shoe. It is also a novel characteristic of the illustrated machine that the wiper-positioning means is mounted for movement about an axis extending heightwise of the shoe to position it in relation to the wiper mechanism; and novelty is likewise to be recognized in provision for similar movement of a shoe-engaging presser foot at the heel end of the shoe which, in the construction shown, is combined with the wiper-positioning means to move therewith.

To facilitate and expedite control of the power operation of the machine, the construction provided by this invention is further such that starting of the machine is effected in response to movement by the operator of a member for engaging or operating on the shoe. As illustrated, a toe presser foot is movable by the operator from an idle position to a position over the shoe, and mechanism is provided for starting the machine by that movement of the presser foot. It is preferable for mechanical reasons that movement of the toe presser foot into position over the shoe be thus effected manually rather than by power, and by utilizing the same movement to start the machine the need for separate starting means and for a separate starting operation are eliminated.

Still another feature relates to control of the shoe by means engaging its bottom portion, as herein illustrated to depress the shoe relatively to lasting mechanism, the construction shown comprising a novel organization including a toe presser foot and a heel presser foot with power-operated means for moving them first into engagement with the shoe and then to depress the shoe.

The above and other features of the invention, including novel means for insuring against accidental or unauthorized movement of the starting mechanism, novel means for insuring against breakage of parts of the machine under possible abnormal conditions, and various novel details of construction and combinations of parts, will now be more par-

ticularly described by reference to the accompanying drawings and pointed out in the claims.

In the drawings,

Fig. 1 is a view in front elevation of a machine in which the invention is embodied, with portions broken away, the machine being shown in this and other views with the parts positioned as they appear at an intermediate stage in the cycle of operations on a shoe;

Fig. 2 is a plan view of the machine, with parts broken away;

Fig. 3 is a vertical section in a plane extending lengthwise of the machine substantially midway between the front and rear thereof;

Fig. 4 is a right-hand end elevation, with parts broken away;

Fig. 5 is a section substantially on the line V—V of Fig. 1;

Fig. 6 is a left-hand end elevation, with parts broken away;

Fig. 7 is a section substantially on the line VII—VII of Fig. 1;

Fig. 8 is a view of the upper right-hand end portion of the machine, partly in front elevation and partly in section;

Fig. 9 is a section on the line IX—IX of Fig. 8, with parts broken away;

Fig. 10 is a view, partly in elevation and partly in section, of a portion of the mechanism shown in Fig. 9;

Fig. 11 is a view in elevation, showing on a larger scale and in greater detail a portion of the structure shown in Fig. 9;

Fig. 12 shows in plan portions of the heel-lasting mechanism as viewed in a location represented by the line XII—XII of Fig. 8;

Fig. 13 shows in plan portions of the same mechanism as viewed in a location represented by the line XIII—XIII of Fig. 8, with parts in section;

Fig. 14 is a section substantially on the line XIV—XIV of Fig. 8, with parts omitted;

Fig. 15 is a view in front elevation of portions of the toe-lasting mechanism;

Fig. 16 is a plan view of the same mechanism with a portion of the cover plate removed;

Fig. 17 shows the toe-lasting mechanism in section in a plane extending centrally through said mechanism lengthwise of the machine;

Fig. 18 is a section on the line XVIII—XVIII of Figs. 1, 3 and 17;

Fig. 19 is a view, partly in front elevation and partly in section, of a toe depressor and retarding device with which the machine is provided;

Fig. 20 is a section on a larger scale on the line XX—XX of Fig. 19;

Fig. 21 is a vertical section, also on a larger scale, on the line XXI—XXI of Fig. 19;

Fig. 22 is a vertical section on an enlarged scale, illustrating more in detail the con-

struction of one of the opposite side-lasting mechanisms and showing the initial position of the mechanism in relation to a shoe;

Fig. 23 is a view similar to a portion of Fig. 22, illustrating the final shoe-engaging positions of the opposite side-lasting mechanisms;

Fig. 24 shows the upper portion of one of the side-lasting mechanisms as viewed from the right-hand side of Fig. 22, with a portion of the casing removed or in section;

Fig. 25 shows shoe-removing mechanism with which the machine is provided, in the position which it occupies when about to grip a shoe;

Fig. 26 is a view, partly in elevation and partly in section on the line XXVI—XXVI of Fig. 3, showing the power driving means and portions of its controlling mechanism; 20 and

Fig. 27 is a section on a larger scale on the line XXVII—XXVII of Fig. 26.

Tennis shoes are usually made on lasts having two spindle holes in their neck portions, 25 of which the rearmost hole is conveniently utilized for positioning the work in the machine herein shown. For this purpose the machine has a last pin 30 (Figs. 3 and 14) which is carried by a slide 32 mounted for 30 adjusting movement in directions lengthwise of the last and shoe in guideways formed in the upper end of a vertically movable supporting slide 34, the slide 34 being depressible with the shoe, as hereinafter described, 35 against the resistance of a spring 36 from an initial raised position determined adjustably by a stop screw 37. The slide 32 is adjustable lengthwise of the shoe by a hand wheel 38 fast on a shaft 40 rotatable in a bracket 42 40 secured on the slide 34, this shaft being connected by bevel-gears 44 to a shaft 46 also rotatable in the bracket 42 and having screw threads engaging a nut 48 fixed in a recess in the slide 32. The last pin 30 is also adjustable 45 in directions heightwise of the shoe to position the bottoms of lasts of different sizes at the same height, and for this purpose it is provided, below that portion which enters the last, with screw threads 50 engaged by co-operating threads of a bevel-gear 52 which 50 is mounted in a bearing in the slide 32. The gear 52 is engaged by a co-operating bevel-gear 54 (Fig. 14) fast on a shaft 56 mounted in a bearing in the slide 32 and extending 55 outwardly through an elongated slot 58 formed in the slide 34, this shaft having on its outer end a hand wheel 60. Suitable means, not shown in detail, is provided for preventing the last pin 30 from turning. It 60 will thus be seen that the means for adjusting the last pin 30 vertically is carried by the horizontally movable slide 32 so that this adjustment may be effected in any position of adjustment of the slide.

The heel-end-lasting mechanism, comprising

ing means more particularly hereinafter described for clamping the upper about the heel end of the last and for wiping its margin inwardly over an insole on the last, is mounted for movement lengthwise of the shoe into and out of operative position. For this purpose there is provided, in the machine herein shown, a supporting slide 62 (Figs. 3 and 8) guided for rectilinear movement lengthwise of the shoe on a pair of horizontal rods 64 70 projecting from the vertically movable shoe support slide 34. The slide 62 is maintained initially in an idle position comparatively remote from the shoe by a latch 66 in engagement with a lug 68 on the lower end of the slide, and upon its release by the latch it is moved toward the shoe by a spring 70 which abuts at one end against a bracket 71 secured to the outer ends of the rods 64. It will be understood that, as above stated, the drawings do not show the parts in their initial positions, but in the positions that they occupy at an intermediate stage in the cycle. The latch 66 is operated manually to release the slide 62 prior to the starting of the power 80 operation of the machine, to cause the clamping of the upper about the heel end of the last before the machine is started. For this purpose there is provided a plunger 72 (Fig. 7) having on its outer end a rubber cushion 74 adapted to be engaged by the knee of the operator, this plunger being movable rearwardly against the resistance of a spring 76. At its inner end the plunger 72 is arranged to abut against a member 78 fast on a bar 80 90 which is movable lengthwise in a bearing formed in a bracket 81 on the frame, this bar being provided with a wedge member 82 arranged to engage a roll carried by a lever arm 84 which is fast on one end of a rock 90 shaft 86. On its other end (Fig. 8) the shaft 86 carries a lever 88 the hub portion only of which is visible in the drawing, this lever having an opening through which loosely extends the lower end of a rod 90 the upper 100 end of which is pivotally connected to a lever 92 which carries the latch 66. On the lower end of the rod 90 is a nut 94 which is engaged by the lever 88 to pull the rod and the latch downwardly and thus to release the slide 62 110 in response to the action of the plunger 72. A spring 96 connected at one end to the rod 90 and at its other end to the slide 62 serves to lift the rod and the latch 66 as far as permitted by the lever 88 and acts also 120 through the rock shaft 86 to position the arm 84 initially in operative relation to the wedge member 82. The latch 66 is adjustably movable along the lever 92, and a screw 97 is provided for adjusting it.

It will be understood that when the slide 62 is released by the latch 66 in the manner above described, the lug 68 on the slide is carried to the left beyond the latch, so that in order to return the slide to its initial posi-

tion it is necessary to move the latch 66 into a position at the left of the lug. For this purpose the lever 92 is pivotally supported at one end on the upper end of a rocker arm 98 mounted on a shaft 100 within a recess in the vertically movable slide 34. At its lower end the arm 98 is formed as a gear sector 102 in engagement with a bevel-gear 104 fast on the upper end portion 106 of a telescopic shaft 108 of which is mounted in a bearing in the frame of the machine and has fast thereon a bevel-gear 110. It will thus be seen that the two parts of the telescopic shaft are connected at all times regardless of the position of the vertically movable slide 34 in which the upper portion 106 of the shaft is mounted. In engagement with the bevel-gear 110 is a gear sector 112 operated by a crank arm 114, this arm being connected by a link 116 (Figs. 3 and 7) to a bell-crank lever 118 mounted on the frame of the machine. The bell-crank lever 118 is connected by a link 120 (Figs. 3 and 5) to an arm 122 fast on a rock shaft 124 and carrying a roll 126 engaged by a path cam 128 formed in one side of a cam wheel 130 which is carried by a cam shaft 132. It will thus be seen that by the mechanism described, in the course of the cycle of operations of the machine, the latch 66 is carried to the left of the lug 68 on the slide 62, the spring 96 yielding to permit the latch to pass the lug, and is thereafter returned toward the right to move the slide 62 and the heel-lasting mechanism carried thereby to its idle position away from the shoe after the operations on the shoe have been completed.

There is also provided, in the machine herein shown, means to enable the operator to return the slide 62 to its initial position in case of its accidental release at any time or in case it should be desired to return it for any other reason prior to the power operation of the machine. This means comprises a chain 134 connected at one end to the slide 62 and extending over a pulley 136 on the bracket 71, the other end of the chain being connected to a rod 138 (Fig. 4) the lower end of which extends loosely through an opening in a treadle 140 pivoted on one end of a rock shaft 142 (Figs. 1 and 7) hereinafter more particularly referred to. On the lower end of the rod 138 is a nut 144 which is acted upon by the treadle to effect the return of the slide 62 to the position in which it is caught and held by the latch 66. The treadle 140 is normally maintained by a spring 146 high enough so that it is not affected by the normal operations of the slide 62, as illustrated in Fig. 4, the upward movement of the treadle being limited by engagement with the lower front casing 148 of the machine at the upper end of a slot in the casing through which the treadle extends.

For clamping the upper to the last about the heel end of the shoe there is provided a

heel band comprising a chain of connected links 150 (Fig. 13) and a leather facing 152, the chain being connected at its opposite ends to blocks 154 each of which is pivotally mounted on one end of an arm 156. Each of the arms 156 is mounted between lugs 158 (Fig. 8) formed on the horizontally movable slide 62 and is fast on a rock shaft 160 mounted to turn in bearings in the lugs. A spring 162 connected to the outer ends of the arms 156 tends to swing apart their other ends to which the heel band is connected and thus to maintain the band initially in an open position. It will be understood that when the supporting slide 62 is moved toward the shoe, as hereinbefore described, the heel band is wrapped about the heel end of the shoe, the pressure of the end face of the shoe on the intermediate portion of the band serving to swing the arms 156 inwardly toward the sides of the shoe against the resistance of the spring 162. To assist in supporting the intermediate portion of the band, the band chain 150 carries a finger 164 (Fig. 13) which is mounted in a recess formed in the slide 62 and is free to swing horizontally in this recess to permit the band to conform itself readily to each shoe regardless of any variations that there may be in the shapes or positions of different shoes.

For wiping the margin of the heel end of the upper inwardly over the insole there are provided heel-lasting wipers 166 (Fig. 12) which are pivotally mounted on a pin 168 carried by the head 170 of a hollow plunger 172 mounted for lengthwise movement and for turning movement in a holder 174. The holder 174 is provided with trunnions 176 mounted in bearings in a yoke-shaped upper end of a plunger 178 (Figs. 8 and 13) which is square in cross-section and is movable vertically in a recess in the slide 62. In the plunger 178 is a spring 180 which tends to move it upwardly, and to limit its upward movement the plunger carries a rod 182 extending downwardly through a bearing in a bracket 184 fast on the slide 62, the rod being provided with a nut 186 for limiting engagement with the bracket. Further supports for the wipers 166 are provided by plungers 188 which are mounted in the heel-band-carrying arms 156 in locations spaced laterally of the shoe and are compressible against the resistance of springs 190 (Fig. 8), the wipers being slidable over the upper ends of these plungers in their operative movements. It will thus be seen that the heel wipers are yieldingly supported by the plunger 178 at the rear thereof and by the two plungers 188 beneath them, and that through the provision of the trunnions 176 and the rotatable plunger 172 they may be tipped about axes extending laterally and lengthwise of the shoe. The plungers support the wipers initially in a plane higher

than their operating plane, and to position them in proper relation to each shoe they are depressed by means hereinafter described.

The heel wipers are advanced lengthwise of the shoe by forward movement of the plunger 172 effected by means also herein-after described, and as they are thus advanced they are closed laterally of the shoe about the axis of the pin 168 by the action of links 192 at the opposite sides of the wiper mechanism, each link being connected at one end to an arm 194 which extends across from the wiper at the other side of the mechanism and being controlled at its other end by a pin 196 mounted in lugs 198 extending laterally from the head of the plunger 178. The pins 196 extend through slots 200 in the links which are provided in order to prevent the wipers from beginning their closing movement until they have been advanced nearly as far as the heel end face of the shoe, so that they will act upon all portions of the margin of the upper around the heel end of the shoe substantially simultaneously. The forward movement of the plunger 172 is effected against the resistance of a spring 202 within the plunger, this spring abutting at its inner end against a lug 204 (Fig. 3) which is fast on the holder 174. It will be understood that this spring acts to return the wipers to their initial positions after they have operated on a shoe, the wipers being opened by the action of the pins 196 on the links 192.

Also supported on the vertically movable slide 34 which carries the shoe is means provided by this invention for clamping the upper against the opposite sides of the last forwardly of the heel end of the last to insure against the possibility, under some conditions, of objectionable displacement of the opposite side portions of the upper by the action of the side-lasting means herein-after described. The use of such clamping means is sometimes desirable in operating on tennis shoes, since it is a frequent practice not to lace the uppers of shoes of this kind prior to the lasting operations. The upper-clamping means comprises, at each side of the shoe, a plurality of spring-metal fingers 206 (Figs. 8 and 14) arranged in a series extending lengthwise of the shoe for yielding engagement with the upper in conformity to the contour of the last, each series of fingers being formed from a piece of sheet metal clamped in a holder 208 pivotally mounted on the end of an arm 210. Each arm 210 is fast on a vertical rock shaft 212 mounted in a bearing in a bracket 214 secured on the upper end of the slide 34. Also fast on each rock shaft 212 is an arm 216, these arms having pin-and-slot connections with the ends of a yoke member 218. Springs 220 connected to the brackets 214 and to the yoke member 218 tend to pull the yoke member

forwardly toward the shoe and thus to swing the arms 210 toward each other to press the fingers 206 against the shoe. For controlling the yoke member 218 there is provided a rod 222 which is pivotally connected to the yoke member midway between the opposite ends of the member and extends outwardly through an opening formed in a lever arm 224 pivoted at 226 (Fig. 8) between upwardly extending arms of the bracket 71. A washer 228 controlled by nuts 230 on the rod 222 engages the arm 224. The lower end of the arm 224 is forked to clear the spring 70 and is arranged to be engaged by the horizontally movable slide 62 when the slide is in its initial position. The slide 62 thus acts initially to hold the sets of clamping fingers 206 considerably farther apart than when they are operating on a shoe, and when the slide is advanced by the spring 70 upon its release by the operator, as hereinbefore described, it releases the arm 224 and thus renders the springs 220 effective to swing the clamping fingers into operative engagement with the sides of the shoe. In the return of the slide 62 to starting position it operates through the arm 224 to move the fingers outwardly away from the shoe. It will be seen that the clamping fingers engage the shoe at a considerable distance below the shoe bottom to provide room for upwiping of the upper by the side-lasting means.

For lasting the toe end of the shoe the machine is provided with mechanism generally similar to that disclosed in the above-mentioned Letters Patent, comprising means for working the upper forwardly on the last, means for wiping it upwardly about the toe to the edge of the insole, and means for wiping its margin inwardly over the insole and for pressing it into position to adhere to the insole. Guided on a bracket 231 on the frame of the machine for adjusting movement lengthwise of the shoe is a slide 232 (Figs. 1, 5 and 15) which has at its opposite sides upwardly extending portions provided with guiding members 234 having curved ribs upon which there is mounted for adjusting movement about an axis extending laterally of the shoe a casing 236. Mounted within a recess in the casing 236 are two metal boxes or holders 238 (Figs. 17 and 18) which rest upon a shelf in the casing and are hinged together by means of a pivot stud 240. In the construction herein shown the stud 240 is threaded in a lug extending from one of the boxes 238 and has its upper end journaled in a lug extending from the other box, the lower end of the stud being enlarged and mounted in a slot 241 (Fig. 18) formed in the casing 236. Secured at their lower ends in each of the boxes 238 are a plurality of upwardly extending leaf springs 242 which have fast on their upper ends metal blocks 244. In

each of the boxes the spring 242 which is adjacent to the hinge joint connecting the two boxes is shorter than the others and is secured in place by a screw 246 in the manner illustrated in Fig. 17, the other springs being secured to the boxes by screws 248. The blocks 244, in the construction herein shown, are provided with slots 249 to receive and support a strip of rubber 250 which is so formed as to extend continuously about the toe of the shoe to serve as a toe band. It will be seen that the strip of rubber has a downwardly extending rib 252 which extends into the slots 249 in the blocks 244 to hold the strip in operative position in such manner that it may be readily removed simply by pulling it upwardly, so that a new strip may be readily substituted when required. When the shoe is depressed, as hereinafter described, the rubber strip or toe band 250 serves as means to wipe the upper upwardly about the toe toward the edge of the insole. In this operation the blocks 244 may yield outwardly, independently of one another, against the resistance of their supporting springs 242. It will be evident, moreover, that these springs prevent the band from yielding unduly in a downward direction and thus render it effective to wipe or draw the upper upwardly in the manner required. In order to increase the resistance to outward yielding movement of the blocks 244, there is mounted within the two boxes 238 in engagement with the springs 242 and the blocks 244 a block of soft rubber 254 which extends continuously from one box to the other and is cut away to clear the hinge joint between the boxes, as illustrated in Fig. 17.

In the above described upwiping operation the boxes 238 which support the toe band 250 may turn as a unit about the axis of the stud 240 and may also shift laterally of the shoe by reason of the slot 241 in which the lower end of the stud is mounted, to permit the toe band to adjust itself to the position of the toe end of the shoe, but they are prevented from moving relatively to each other in that operation by means of a rod 256 which has thereon right and left-hand screw threads in engagement with studs 258 which are swiveled in the bottoms of the boxes, this rod projecting outwardly through a slot 260 in the casing 236 and serving as means whereby the two boxes may be relatively adjusted for shoes of different widths. To assist in preventing tipping movement of the boxes 238 and in guiding them in their swinging movements they carry pins 262, one of which projects outwardly through the slot 260 in the casing 236 and the other through a slot 264 in the casing.

The means for working the upper forwardly on the last in the upwiping operation comprises a rubber toe rest 266 which engages the upper on the top of the forepart

and is depressed by the downward movement of the shoe, the toe rest receiving a forward upper-pulling movement in the first part of its downward movement. The toe rest 266 is mounted on the upper end of a hollow plunger 268 slidably mounted in a holder 270 which, by means of pivot studs 272 at its opposite sides, is mounted on the casing 236 for swinging movements lengthwise of the shoe. A spring 274 mounted in the holder 270 and within the hollow plunger 268 serves as yielding means against the resistance of which the toe rest is downwardly movable. For imparting to the toe rest swinging movement to pull the upper forwardly on the last in response to the downward movement of the plunger 268, there is provided a cam member 276 secured to a bracket 278 which is fast on the casing 236, the member 276 having a cam face 280 for engagement with a roll 282 carried by the plunger 268 and the roll being supported on a member 284 which projects through a slot in the holder 270. On its upper end the member 276 is provided with a projection 286 which engages the roll 282 to limit upward movement of the toe rest. Below the cam face 280 the member 276 is provided with a straight face 288 which is engaged by the roll 282 during continued downward movement of the toe rest after its upper-pulling movement produced by the cam face 280 has ceased. The spring 274 is a comparatively light spring which holds the toe rest 266 against the shoe with sufficient friction to render it effective to pull the upper forwardly as required during that part of the downward movement of the toe rest in which the pulling of the upper takes place. At the end of this pulling movement, as soon as the roll 282 arrives in position to engage the straight face 288 of the cam member 276, a heavier spring 290, which is seated within the holder 270 below the end of the plunger 268, becomes effective to oppose increased resistance to downward movement of the toe rest and thus to hold it against the shoe with heavier pressure and thereafter, as more particularly hereinafter described, to force the shoe upwardly against the wipers for pressing the margin of the upper upon the insole. For controlling the holder 270 in such manner as to maintain the roll 282 in engagement with the cam member 276, there is provided a spring-controlled plunger 292 mounted in a recess formed in an extension 294 of the holder, this plunger engaging the lower end of the member 276.

The means for wiping the margin of the toe end of the upper inwardly over the insole comprises toe-embracing wipers consisting of a pair of end wiper plates 296 (Fig. 16) having wiping edges curved to embrace the upper around the end of the toe and a pair of additional wiper plates 298 arranged to act only at the sides of the toe. The end plates 296

are mounted for swinging movements on a pivot stud 300 which is carried by a slide 302 mounted for movements lengthwise of the shoe in guideways provided on the casing 236. The plates 296 are thus mounted for advancing movement lengthwise of the shoe and for closing movements laterally of the shoe. The side wiper plates 298, on the other hand, are so mounted as to have only movements laterally of the shoe, and for this purpose are provided with arms 304 pivotally mounted at 306 on the casing 236. The wiper plates 298 have comparatively thin wiping portions arranged to underlie the plates 296, and the latter plates in their operative movements advance over the upper or outer faces of the plates 298. This arrangement of wiper plates assists in guarding against any undue bending of the margin of the upper rearwardly at the sides of the toe.

Advancing movement lengthwise of the shoe is imparted to the wiper plates 296 by a crank arm 308 (Fig. 17) which is fast on a rock shaft 310 mounted in the casing 236 and is provided with a roll 312 mounted between lugs 314 extending downwardly from the slide 302. The rock shaft 310 is operated by mechanism hereinafter described. For imparting closing and opening movements to the wiper plates 296 and 298 at each side of the wiper mechanism there is provided a gear sector 316 pivotally mounted on the casing 236 and having thereon a roll 317 for engaging and closing the side wiper 298, a pin 318 arranged to act through a link 320 to impart closing and opening movements to the end wiper 296, and a pin 322 arranged to act through a link 324 to impart opening movement to the side wiper 298. Each of the gear sectors 316 is operated by a rack member 326 slidably mounted in the casing 236 and provided with rack teeth engaged by a gear sector 328 on the rock shaft 310. The pins 318 operate in slots formed in the links 320 for the purpose of delaying the closing of the end wipers 296 until after the side wipers have begun their closing movement, and the lugs 314 (Fig. 17) are also spaced to cause a corresponding delay in the advance of the end wipers, an object of this construction being to permit the side wipers to be spaced initially far enough apart to allow for variations in the widths of shoes of different sizes and yet to prevent the end wipers from beginning their wiping action ahead of the side wipers. In the links 324 slots are provided to permit the pins 322 to move relatively to the links in the closing of the wipers.

Associated with the above-described toe-lasting wipers is auxiliary lasting means similar to that disclosed in Letters Patent No. 1,778,192, granted upon an earlier application of mine on October 14, 1930, arranged to act at the ends of the wipers to lay the margin of the upper inwardly over the insole without any substantial wiping effect thereon and also to press the margin of the insole down upon the bottom of the last in those locations. An object thus in view is to assist in insuring that portions of the margin of the insole along the sides of the toe will not be so positioned as to be in danger of being displaced by the wiping action of the wipers, and the use of such means is especially desirable in operating on tennis shoes, since in shoes of that kind it is customary to use insoles which are comparatively soft and yieldable and are not fastened to the lasts. For the purpose in view there are provided flexible lasting straps 330 (Figs. 5 and 16), preferably made of leather, which are connected to the side wiper plates 298 and are operated thereby to lay or fold the margin of the upper over the insole without any substantial wiping action and to press the insole upon the bottom of the last. These straps are arranged to extend upwardly and outwardly over upraised portions 332 of the wiper plates 298 and are received in recesses 334 in these wiper plates as the latter are moved inwardly over the shoe, these recesses being so arranged that the portions of the upper-engaging faces of the straps which are parallel to the outer face of the insole at the end of the overlaying operation are in substantially the same plane as the wiping faces of the wipers 298. At their upper ends the straps 330 are connected to slides 336 movable in guideways in the upraised portions 332 of the wipers against the resistance of springs 338, these springs being arranged to yield in the overwiping operation to permit the wipers to move relatively to the straps, while also maintaining the straps in a tight condition. At their lower ends these straps are fastened to holders 340 by the action of which they are pressed against the sides of the shoe, these holders being pivotally mounted on the upper ends of carriers 342 provided with depending shanks which are swiveled in arms 344 for movements about axes extending heightwise of the shoe to permit the holders 340 to adjust themselves to the lengthwise contour of the shoe. The arms 344 are pivoted at 346 on the bracket 278 for swinging movements laterally of the shoe and are pulled toward each other by a spring 348, the movements of the arms toward each other when there is no shoe in the machine being limited by stop screws 350 in the bracket 278. It will thus be seen that initially the lower ends of the straps 330 and the holders 340 underlie the side portions of the shoe in the path of downward movement of the shoe, so that they serve to wipe the upper upwardly toward the edge of the insole and to tighten it over the forepart of the last simultaneously with the upwiping action of the toe band 250. It will also

be seen that the portions of the straps 330 which are secured to the holders 340 are wider than the portions engaged by the wiper members 298, so that these wider portions serve to upwipe the upper also in locations underneath portions of the wiping edges of the wipers 298, these portions of the straps thus serving in effect as extensions of the toe band. In the upwiping action of the straps as the shoe is depressed, the holders 340 are spread apart against the resistance of the spring 348, and thereafter the straps are pressed by the holders against the sides of the shoe to hold the upper in its upwiped condition while the straps are being operated to lay the margin of the upper over the insole. In this overlaying operation the straps are bent about the edge of the shoe bottom and act to press the margin of the insole down if it happens to be upraised from the bottom of the last and to hold it against any tendency of the wipers to displace it.

From the foregoing description it will be evident that the casing 236, adjustable on the curved guide members 234, serves to support the toe band 250, the toe-lasting wipers 296 and 298 with their straps 330, and the toe rest 266. The members 234 are so formed and arranged that these parts are adjustable about an axis extending laterally of the shoe and so located that the toe wipers may be properly positioned in accordance with the lengthwise slope of the bottom of the fore-part of the last without altering materially the height of the wipers as a whole. For effecting this adjustment there is provided a hand wheel 352 fast on a shaft 354 mounted in bearings in the slide 232, this shaft being connected by bevel-gears 356 (Fig. 17) to a shaft 358 mounted in a bearing in a holder 360 which is swiveled on the shaft 354. The shaft 358 is provided with screw threads in engagement with co-operating threads in a stud 362 swiveled in the casing 236. It will be understood that by this means the operator will adjust the toe-lasting mechanism to position the toe wipers in such relation to the shoe as to apply substantially uniform pressure to the different portions of the margin of the upper along the sides of the toe in accordance with the requirements of the line of shoes on which the machine is to operate. It is desirable that the operator be afforded some definite indication as to the condition of the toe-lasting mechanism in respect to such adjustment, and for this purpose there is provided a pointer 364 (Fig. 15) pivoted on a bracket 366 which is fast on the slide 232, this pointer being connected by a link 368 to the casing 236 and movable along a scale provided on the bracket 366. It will be understood that the numbers on the scale have no relation to shoe sizes, and simply serve to indicate to the operator whether the adjustment at any time is the same as that

previously noted as correct for the line of shoes on which the machine is operating.

Adjustment of the slide 232 along its guideway on the frame to vary the position of the toe-lasting mechanism for shoes of different lengths is effected by a hand wheel 370 fast on a shaft 372 (Fig. 18) journaled in a bearing on the frame of the machine, this shaft being connected by bevel-gears 374 to a shaft 376 which is threaded for engagement with a lug 378 (Figs. 1 and 15) on the slide 232.

The downward movement of the shoe to effect the upwiping of the upper at the toe by the toe band 250 and the forward pulling of the upper by the toe rest 266 in the manner hereinbefore described is effected by a toe presser foot 380 and a heel presser foot 382 (Fig. 3) which engage the insole at its toe and heel ends respectively and serve to depress the shoe-supporting slide 34 against the resistance of its spring 36 and the toe rest 266 against the resistance of its supporting springs 274 and 290. The heel presser foot 382 is supported and operated by means hereinafter described. The toe presser foot 380 is carried by an arm 384 mounted in a holder 386 which is carried by a toe post comprising upper and lower rods 388 and 390 arranged in alinement with each other and mounted for vertical movements and also for turning movements in bearings in the frame. The rod 390 is swiveled at its lower end in a coupling member 392 which is connected by a link 394 (Fig. 5) to one end of a lever 396 fast on the rock shaft 124 previously referred to as operated by the cam 128 through the arm 122, this being the rock shaft which operates the latch 66. It will thus be seen that when the rock shaft 124 is operated by the cam to move the latch 66 toward the left (Fig. 3) the toe presser foot 380 also is moved downwardly to depress the shoe, and that at the end of the cycle the return upward movement of the presser foot coincides with the movement of the latch to return the slide 62 of the heel-lasting mechanism to its idle position, as described.

By reason of the provision for turning movement of the rods 388 and 390 in their bearings the toe presser foot 380 may be swung in a horizontal plane into and out of position over the toe end of the shoe. Initially, in the machine herein shown, this presser foot is maintained in an idle position at the rear of that which it occupies when over a shoe by a spring 398 (Figs. 6 and 18) which acts on a collar 400 encircling the rod 390 and carrying a roll 402 mounted in a vertical slot 404 (Fig. 3) in the rod. The collar 400 is supported on that portion of the frame which provides a bearing for the rod 390 and is prevented from moving upwardly by means of a bracket 406 secured on the frame and forked to embrace the rod 390. The

spring 398 is supported on a rod 408 and bears at one end on a block 410 which is mounted between spaced lugs on the collar 400 and is provided with pins 412 mounted in recesses in these lugs. The rod 408 extends loosely through an opening in a bearing member 414 against which the spring 398 abuts, this member being threaded in the frame and adjustable to vary the compression of the spring.

10 It is intended that the operator shall swing the presser foot 380 forwardly into position over the shoe, and for this purpose there is provided a handle 416 on the arm 384. To determine the proper position of the presser foot when over the shoe there is provided means for limiting its swinging movement, comprising a roll 420 carried by a collar 422 (Fig. 3) fast on the rod 390 and arranged for limiting engagement with a plate 424 fast on the frame of the machine. From the position to which the operator thus swings the presser foot 380 it receives its downward movement, in the machine herein shown, entirely by power through the operation of the connections hereinabove described to the rock shaft 124. To enable the operator to release the handle 416 after the machine has started, there is further provided means for locking the rod 390 in the position to which the operator has turned it, comprising a member 426 co-operating with the plate 424 to provide a vertical slot for the roll 420, as illustrated in Fig. 6. The member 426 at its upper end has a sloping cam face 428 which will act on the roll 420 to insure the proper position of the presser foot if the operator releases the handle 416 too soon and also serves to control the roll in the return of the parts to their idle positions to prevent the presser foot arm 384 from being swung too abruptly to the rear of the machine by the action of the spring 398. The upper end portion of the cam face 428 also acts as a stop for the roll 420 when the parts are in their initial positions.

As illustrated in Fig. 21, an adjustable connection is provided between the holder 386 and the rod 390, whereby the height of the presser-foot-supporting arm 384 may be varied. For this purpose the reduced upper end of the rod is mounted in a split bearing in the lower end of the holder and has threaded therein a screw 430 the head of which is swiveled in an opening in the holder and is provided with a plurality of holes 432 adapted to receive a suitable tool inserted through a slot in the holder for turning the screw. A stud 434 screwed into the holder 386 with its end projecting into a slot in the rod 390 prevents relative turning movement of the rod and holder. A set screw 436 may be tightened to prevent the screw 430 from turning, and the parts of the split bearing also may be drawn together by

screws, as illustrated, to clamp the parts securely together after adjustment.

It will be evident that the above-described connections between the rod 390 and the holder 386 provide means for adjusting heightwise of the shoe the arm 384 which carries not only the presser foot 380 but also means hereinafter described for controlling the insole and the margin of the upper at the toe end of the shoe. The machine is further so constructed as to enable the operator to effect quickly an adjustment of the presser foot alone heightwise of the shoe relatively to the arm 384. For this purpose the presser foot is mounted on a slide 438 (Figs. 19 and 20) vertically movable in a guideway in the end of the arm 384, and for adjusting this slide there is provided an arm 440 fast on a shaft 441 rotatable in the arm 384 and having thereon an eccentric 442 movable in a slot formed in the slide 438. For maintaining the slide in adjusted position there are provided in the arm 384 a plurality of holes 444 arranged to receive a spring-controlled pin 445 carried by the arm 440. The presser foot 380 is mounted for turning movement on a stud 446 in the slide 438 so that it may adjust itself to the lengthwise contour of the shoe bottom, such movement of the presser foot being limited by a spring plunger 448 mounted in the slide and engaging the hub of the presser foot in a recess 450 formed therein.

Supported also on the arm 384 is means similar to that disclosed in the above mentioned Letters Patent No. 1,775,225 for engaging the insole about the toe to press its margin close to the bottom of the last and for also assisting the toe wipers in wiping the margin of the upper tightly inward over the insole. This means comprises a member 452 (Figs. 19 and 20) curved similarly to the edge of the toe end of the insole and supported on the arm 384 by means including an arm 454 and links 456 and 458. The arm 454 extends generally lengthwise of the shoe and is forked at one end and connected to the member 452 by pivot studs 460 so that the member 452 is permitted to tip about an axis extending laterally of the shoe to adjust itself to the lengthwise contour of the shoe bottom. The links 456 and 458 are pivotally connected to the arm 454 at their lower ends, and at their upper ends they are pivotally connected respectively to the arm 384 and to a plunger 462 mounted for vertical movement in the arm 384 against the resistance of a spring 464 extending into the handle 416. A spring 466 connected to the link 456 and to a pin on the arm 384 tends to position the parts as shown in Fig. 19, while permitting the arm 454 to be swung by the links 456 and 458 to carry the member 452 forwardly toward the end of the toe of a shoe, the plunger 462 also being upwardly yieldable in response to engagement of the member with

the shoe. Such forward movement is imparted to the member 452 in response to the downward movement of the arm 384, and for this purpose the link 456 is provided at its upper end with a gear sector 468 engaged by a rack bar 470 vertically movable in the arm 384 and having in an offset portion at its lower end an adjustable screw 472 projecting downwardly below the arm. For controlling the rack bar 470 there is provided means substantially as illustrated in another copending application Serial No. 226,399, filed on October 15, 1927, comprising a bracket 474 (Figs. 1 and 2) which is fast on the frame of the machine and into engagement with which the screw 472 is carried in the downward movement of the arm 384. It will be understood that when the arm 384 receives its downward movement to carry the presser foot 380 into engagement with the insole and to depress the shoe, the member 452 is carried into engagement with the insole, the spring 464 then yielding to permit the presser foot to seat itself upon the insole before the screw 472 engages the bracket 474. Thereafter, in response to engagement of the screw with the bracket as the shoe is depressed by the presser foot, the member 452 is carried forwardly toward the toe end of the insole by the link 456, the plunger 462 further yielding upwardly as required while pressing the member 452 firmly down upon the insole. In this manner the margin of the insole around the toe is smoothed out and pressed close to the bottom of the last preparatory to the overwiping operation of the toe wipers. Furthermore, as the wipers wipe the margin of the upper inwardly over the insole, the margin of the upper also is engaged by the member 452 which acts as a retarder to increase the frictional hold of the wipers on the upper. It will be noted that the member 452 presents an outwardly flaring face 476 (Fig. 19) for engagement with the margin of the upper, and by reason of this construction the member is wedged upwardly by the wipers against the resistance of the spring 464 to permit the wipers to wipe the upper flat upon the insole beneath the member.

It will be evident that, corresponding to adjustment of the toe-lasting mechanism lengthwise of the shoe by the hand wheel 370, as hereinbefore described, the arm 384 with its presser foot 380 and insole and upper-controlling member 452 should be also adjusted in order that these parts may be positioned properly in relation to the toe ends of shoes of different lengths. The machine is accordingly provided with means substantially as disclosed in application Serial No. 226,399 whereby the arm 384 is adjusted simultaneously with the slide 232 of the toe-lasting mechanism by the same hand wheel 370. For this purpose there is connected to the slide 232 a rack bar 478

(Figs. 6 and 18) which engages a pinion 480 on a short shaft 482 connected by a universal joint (not shown) to a telescopic shaft 484 (Fig. 21), this shaft being connected by a universal joint to a short shaft 486 mounted in a bearing in a plate 488 secured on the holder 386. The shaft 486 carries a pinion 490 connected through an idle pinion 492 to rack teeth 494 on the arm 384. It will thus be seen that as the toe-lasting mechanism is adjusted lengthwise of the shoe the arm 384, which is slidably mounted in the holder 386, is correspondingly adjusted. It will further be evident that by reason of the connections including the telescopic rock shaft 484 and its universal joint connections with other parts of the adjusting means, the adjustment of the arm 384 is not affected by the vertical movements of the holder 386 in the operation of the machine.

The heel presser foot 382, which is operated in conjunction with the toe presser foot 380 to depress the shoe, is supported by a movable head or carrier 496 fast on a vertical rod or post 498 mounted in bearings in the frame of the machine. The presser foot is pivotally mounted on a slide 500 (Fig. 3) which is vertically adjustable in a guideway formed in a casting 502 mounted by means of screws 504 and washers 505 (Figs. 9 and 10) on the carrier 496. The slide 500 is held upwardly by a spring 506 against the lower end of a stop screw 508 which is adjustable in the casting 502 to vary the height of the presser foot relatively to the carrier 496. The rod 498 is swiveled at its lower end (Fig. 4) in a coupling member 510 which is connected by a link 512 to one arm of a bell-crank lever 514 mounted for turning movement on a shaft 516, the other arm of this bell-crank lever being connected by a link 518 to an arm 520 fast on the rock shaft 124 which, as already described, serves as means for operating the toe presser foot 380. It will thus be seen that the toe presser foot and the heel presser foot are operated simultaneously by the rock shaft 124 to depress the shoe.

The rod 498 is mounted not only for vertical movements, but also for turning movements in its bearings to swing the carrier 496 either to an operative position with the presser foot 382 over the heel end of the shoe or to an idle position with the presser foot at the rear of the heel end of the shoe. For thus swinging the carrier there is provided mechanism similar to that shown in Fig. 18 for controlling the toe presser foot 380 and its supporting means, comprising a collar 522 (Fig. 9) which carries a roll 524 mounted in a vertical slot in the rod 498, a rod 526 connected to the collar 522 and extending loosely through a bearing member 528 in the frame of the machine, and a spring 530 on the rod which acts normally to maintain the carrier 496 in its idle position. At the beginning of

the downward movement of the rod 498 the carrier 496 is swung from its idle position to carry the presser foot 382 to its operative position over the shoe by a cam member 532 which is fast on the frame and engages a roll 534 on the carrier. Swinging movement of the carrier in response to the action of the cam 532 is limited by engagement of the head of a stop screw 536 on the carrier with a vertical face 538 on the frame of the machine. To maintain the carrier 496 in its operative position after it has been swung to that position, the cam 532 is provided with a vertical face 540 for engaging the roll 534. It will be understood that the carrier 496 is thus swung by the cam 532 quickly to a position in which the presser foot 382 is over the heel end of the shoe at the beginning of the downward movement of the rod 498 before the presser foot has been carried downwardly far enough to engage the shoe.

As hereinbefore stated, the heel wipers 166 are positioned initially in a higher plane than their operating plane by the spring plunger 178 in the slide 62 and the two spring plungers 188 in the heel-band-supporting arms 156. Depression of the wipers into proper relation to the heel end of the insole is effected by the downward movement of the presser foot carrier 496, the wipers being thus positioned at a height relatively to the shoe determined by engagement of the presser foot 382 with the insole. For this purpose the carrier 496 is provided with a screw 542 (Figs. 3 and 8) which engages a plate 544 mounted on the plunger 178, and acts in line with this plunger substantially midway between the opposite sides of the wiper mechanism, and the casting 502 on the carrier 496 is provided with members 546 spaced apart laterally of the shoe for engaging the wiper plates 166 over the plungers 188. The members 546 and the screw 542 also control the wipers in respect to tipping movements about axes extending lengthwise and laterally of the shoe respectively, and it will be evident that by adjusting the screw 542 the position of the wipers in respect to inclination lengthwise of the shoe may be variably determined. It is desirable that the position of the wipers in respect to tipping movement about a longitudinal axis be determined by the shoe itself, and to this end the casting 502 which carries the presser foot 382 and the wiper-engaging members 544 is so mounted as to rock laterally of the shoe to a position determined by engagement of the presser foot with the bottom of each shoe, the casting having therein slots 548 whereby it is supported on rolls 549 mounted on the screws 504 (Figs. 9 and 10). It will also be evident that the presser foot 382 determines the distance between the plane of the wiping faces of the wipers and the bottom face of the insole, and that by vertical adjust-

ment of the presser foot through the screw 508 the amount of pressure applied by the wipers over the heel end of the insole may be varied and accurately determined.

For imparting operative movement to the rock shaft 310 to operate the toe wipers 296 and 298, there is provided on the end of the shaft a bevel-gear 550 (Figs. 5 and 18) in engagement with a co-operating bevel-gear 552 fast on a shaft 554 mounted in a bearing on the rear of the adjustable casing 236. The shaft 554 is connected by a universal joint to a telescopic shaft 566 which is connected in turn by another universal joint to a coupling member 558 adjustably connected to a co-operating member 560 fast on a shaft 562 mounted in a bearing on the frame of the machine. The shaft 562 carries a bevel-gear 564 in engagement with a gear sector 566 fast on the rock shaft 516 previously mentioned as loosely supporting the bell crank 514 (Fig. 4). Also fast on the shaft 516 is a gear sector 570 engaged by a gear sector 572 mounted to turn on the shaft 124 and having secured thereto a lever arm 574 provided with a roll 576 (Fig. 3) engaged by a path cam 578 formed in one side of the cam wheel 130. It will thus be seen that operative connection between the cam 578 and the toe wipers is maintained in all positions of adjustment of the wiper-supporting means. The connection between the two coupling members 558 and 560 comprises a bolt 580 which extends through a slot 582 (Fig. 2) in the member 558, so that a turning movement of this member relatively to the member 560 may be effected for adjusting the toe wipers in the direction of their operative movement to determine the distance that they wipe the upper inwardly from the edge of the insole, this adjusting means serving to vary both the limit of advancing movement of the wipers 296 and the limit of closing movement of these wipers and of the wipers 298.

Operative movement of the heel wipers 166 is effected simultaneously with that of the toe wipers by operation of the same rock shaft 516 which, as above stated, is operated by the cam 578. For this purpose there is fast on the shaft 516 a lever arm 584 (Figs. 7 and 8) pivotally connected to a curved bar 586 which is secured at its upper end to the lower end of a rod 588, the upper end of this rod being pivotally connected to one arm 590 of a bell-crank lever mounted for turning movement on a rod 592 on the frame of the machine, the other arm 594 of this lever being arranged to engage the outer end of the spring plunger 172 previously referred to as part of the means for advancing and closing the heel wipers. It will be seen that, irrespective of variations in the position of the heel wipers, the arm 594 is operative to advance the plunger 172 after the wipers have

been positioned in proper relation to the shoe and depressed with the shoe by the operation of the member 496.

For lasting the sides of the shoe between the toe and heel end portions the machine is provided with opposite side-lasting mechanisms which are in many respects similar to the construction shown in the above-mentioned Letters Patent No. 1,775,225 and in other respects present novel features. Each of these mechanisms comprises a support or casing 596 (Figs. 7 and 22) mounted to swing toward and from the shoe on a rod 598 which is movable to carry the casing lengthwise of the shoe and thus to shift the position of the side-lasting mechanism toward the toe end of the shoe between successive operations on the shoe, there being two of the rods 598, one for each of the opposite side-lasting mechanisms, mounted for lengthwise movement in bearings in the frame of the machine. Mounted to swing about each rod 598 within the casing 596 is an arm 600 arranged to control a plurality of sets of lasting devices, herein shown as four in number. Each of two of these sets of lasting devices comprises a strap 602 of flexible material, preferably leather, arranged to extend generally heightwise of the shoe and connected at its upper end to a lasting finger 604 supported on the arm 600 and extending transversely of the arm while the other two sets have a single strap in common connected to two such lasting fingers. Each set of devices is provided with a side presser comprising an arm 606 pivotally mounted at 608 on the casing 596 to swing toward or from the shoe and having pivotally mounted at 610 on its upper end a block 612 provided with an inner face curved similarly to the heightwise contour of the side of the shoe and arranged to press the strap against the shoe, the lower end of the strap being fastened to the block. Two of the arms 606 are engaged by spring plungers 614 mounted in the casing 596, which tend to swing the upper ends of the arms inwardly toward the shoe, the limit of such inward swinging movement of the arms when there is no shoe in the machine being determined by a plate 616 on the casing 596 in engagement with fingers 618 on the arms. For swinging the other two arms 606 inwardly there are provided springs 620 connected to the casing 596 and to fingers 622 on these arms, the fingers 622 also engaging the plate 616 to limit swinging movement of the arms. It will thus be evident that when the opposite side-lasting mechanisms are carried inwardly against the sides of the shoe, the plungers 614 and the springs 620 yield more or less as the lasting devices adjust themselves to the contour of the shoe and serve thereafter to press the straps 602 yieldingly against the sides of the shoe. The several straps of each of the side-lasting mecha-

nisms are so arranged that they effect a substantially continuous engagement with the upper lengthwise of the shoe.

Each of the lasting fingers 604 has a slot 623 extending lengthwise thereof, and through the slots in the several fingers of each set of lasting devices extends a rod 624 carried by a holder 625 on the arm 600, by which the fingers are supported on the arm. Within the slot in each finger is a spring plunger 626 engaging the rod 624 and through which the arm 600 acts to force the finger yieldingly inward over the shoe. The straps 602 are connected at their upper ends by screws 628 to plungers 630 slidably movable in guideways in the fingers 604, the screws extending through slots in the fingers, and controlling the plungers 630 are springs 632 which are yieldable to permit the fingers to slide along the straps as they are moved inwardly over the bottom of the shoe and also to assist in maintaining the straps in a tight condition. Underlying each of the fingers 604 is a spring plunger 634 mounted in the holder 625, which tends to swing the finger upwardly about the rod 624 and thus also assists in holding the strap tight. It will be understood that, by means more particularly hereinafter described, each casing 596 and its arm 600 are swung inwardly to carry the straps 602 against the side of the shoe, and that by further movement of the arm, after the straps have been utilized as hereinafter described to upwipe the upper, the fingers 604 are forced yieldingly inward over the bottom of the shoe while the straps are pressed against the side of the shoe by the blocks 612. As the fingers are thus forced inwardly, they are swung downwardly toward the bottom of the shoe against the resistance of the plungers 634 in response to the pull of the straps thereon, the springs 632 yielding to permit the fingers to move inwardly along the straps. Connecting the casings 596 together is a spring 636 (Fig. 7) which tends to swing the casings inwardly toward the shoe and against the resistance of which they are held initially in their outer positions by the arms 600, each arm having for this purpose a stud 638 which projects through a slot 640 in the casing 596 and engages the casing at one end of the slot. For controlling and operating the arms 600 there are provided toggle links or arms 642 which are pivotally connected to the arms 600 and are pivotally and slidably mounted at their inner ends on a rod 644. The rod 644 is supported in the upper ends of spaced arms of a link member 646 (Fig. 3), this member being pivotally connected at its lower end to a lever arm 648 (Fig. 7) pivoted at 650 on the frame of the machine. The arm 648 is connected to a lever arm 652, pivotally mounted on the previously mentioned rock shaft 124, by a two-part link, one part 654 of which is connected to the arm 648

and is hollow to provide a housing for a plunger 656 on the end of a rod 658 which is connected to the arm 652. A spring 660 engaged by the plunger 656 is arranged to be compressed by downward movement of the rod 658 relatively to the member 654 to afford a yielding operating connection between the two arms 648 and 652. The arm 652 carries a roll 662 engaged by a path cam 664 formed 10 in one side of a cam wheel 666 on the cam shaft 132. It will thus be understood that, when permitted by the controlling mechanism described, the spring 636 operates to swing the opposite side-lasting mechanisms 15 inwardly into engagement with the sides of the shoe, and that thereafter further inward swinging movements are imparted yieldingly to the arms 600 through the spring 660 to force the lasting fingers 604 inwardly over 20 the bottom of the shoe. It will be seen that the cam 664 is so shaped as to impart such inward movement to the arms twice in each cycle of operations and to swing the side-lasting mechanisms outwardly away from 25 the shoe between the two inward movements of the arms to permit these mechanisms to be advanced lengthwise of the shoe from their first operating position to their second operating position, as more particularly hereinafter described. For centralizing the rod 644 when the side-lasting mechanisms are in their outer positions there are provided cam plates 667 (Figs. 3 and 5) arranged to engage a roll 668 on the rod. 30

As stated above, when the lasting fingers 604 are moved inwardly over the bottom of the shoe, the straps 602 exert a downward pull thereon to cause them to apply through the straps downward pressure on the shoe bottom. The machine herein shown is provided with novel means for further operating the fingers 604 to press their inner end portions downwardly toward the shoe bottom, this means being arranged to act independently of the straps to swing the fingers heightwise of the shoe as they are moved inwardly over the shoe. For the purpose in view each of the toggle arms 642 has an extension 669 rigid therewith and projecting 45 beyond its pivotal connection with the arm 600, each extension 669 being pivotally connected to a sleeve member 670 slidably mounted on a thimble 672 which is slidable on a rod 674. The upper end of each rod 50 674 has fast thereon a holder 676 positioned between spaced lugs 678 on the adjacent arm 600, a pin 680 being provided to maintain the holder in place between the lugs. Pivoted on a stud 682 (Fig. 24) at the upper 55 end of each holder 676 is a rocker arm 684 having at its opposite ends studs 686 on which are pivotally mounted members 688 arranged to engage the lower faces of the outer ends of the lasting fingers 604. Between the lower end of each holder 676 and the head of the thimble 672 is a spring 690 through which upward movement is imparted yieldingly to the holder by the sleeve member 670, the member 670 being arranged to engage the lower face of the head of the thimble. A nut 692 threaded on the lower end of the rod 674 and held thereon by a lock nut 694 is adjustable to vary the compression of the spring 690. Each rocker arm 684 is provided centrally with a lower flat face 70 engaged by the upper end of a spring plunger 696 in the holder 676, this plunger tending to hold the arm in a central position with respect to tipping movement about the stud 682, while permitting it to tip as may be required to force one or more of the lasting fingers farther downwardly than the others in accordance with the contour of the bottom of the shoe. It will be understood that this rocker arm and the members 688 pivoted thereon provide means for substantially equalizing the pressures applied to the shoe by the different lasting fingers controlled thereby. It will further be evident that the upward movements of the sleeve members 670 for imparting yieldingly through the springs 690 the swinging movements to the lasting fingers 604 occur simultaneously with the swinging movements of the arms 600 to force the fingers inwardly over the shoe bottom, in response to the progressive swinging movements of the extensions 669 which act as lever arms to lift the sleeve members. As will be seen by reference to Fig. 22, the finger-engaging members 688 are spaced initially below the outer ends of the fingers to allow for such movement of the toggle arms 642 as results from the inward movements of the side-lasting mechanisms effected preliminarily by the spring 636 to clamp the upper on the sides of the last (Fig. 7). Thereafter, as the arms 600 are swung inwardly by further movement of the toggle arms 642, the means for swinging the lasting fingers to press the upper upon the insole is operated at the same time by the movement of the toggle arms, the arrangement being such that the fingers are swung into upper-pressing positions early in their inward movement over the shoe, substantially as soon as they have crossed the edge of the insole, and are then operated to increase the pressure progressively in their further inward movement. 100

Before the opposite side-lasting mechanisms are operated in the manner above described to lay the margin of the upper inwardly over the insole in the first operating position of these mechanisms, at the shank portion of the shoe, they are utilized to wipe the upper upwardly at the sides of the last in response to the previously described downward movement of the shoe, the arrangement being such that they are carried inwardly into engagement with the sides of the shoe prior to 105 110 115 120 125 130

the depression of the shoe. As previously mentioned, in shoes of the type illustrated the insole is not fastened to the bottom of the last, and it is accordingly considered preferable that the opposite side-lasting mechanisms be moved inwardly into engagement with the shoe prior to the starting of the power operation of the machine, while the operator can still control the insole, in view of possible danger that there might otherwise be of relative displacement of the insole and the last by the movement of these mechanisms into engagement with the shoe. There is accordingly provided means whereby the side-lasting mechanisms may be released to the action of the spring 636 independently of the power operation of the machine. To this end, that portion of the path cam 664 where the roll 662 is located at the beginning of the cycle of the machine is enlarged, as indicated at *a* (Fig. 7), to permit the lever arm 652 to be moved independently of the cam prior to the starting of the machine. There is also provided means which is operative independently of the cam 664 to hold the side-lasting mechanisms in their initial outer positions. This means comprises an arm 698 (Fig. 7) mounted to swing on the previously mentioned rock shaft 86 as a bearing, the upper end of this arm being arranged to act as a catch to engage and hold the outer end of the lever arm 648 in its initial upper position with the side-lasting mechanisms swung out away from the shoe. A spring 700 is connected to the lower end of the arm 698 to hold it in operative position against the end of a stop screw 702 mounted in the bracket 81. Conveniently the arrangement is such that the arm 698 may be operated to release the side-lasting mechanisms by the same plunger 72 which is provided, as previously described, for releasing the slide 62 of the heel-lasting mechanism to cause that mechanism to advance into operative relation to the shoe. The arm 698 is accordingly so positioned that its lower end is engaged by the end of the bar 80 as this bar is pushed inwardly by the plunger 72, to cause the arm to release the lever 648. Preferably however, as illustrated, the arrangement is such that the bar 80 does not engage the arm 698 until after the wedge 82 has acted to release the heel-lasting mechanism in the manner hereinbefore described. Accordingly, as the operator pushes the plunger 72 inwardly, the heel-lasting mechanism is first released, and thereafter by further inward movement of the plunger the side-lasting mechanisms are released. It will be evident that, if the operator so desires, he may thus release only the heel-lasting mechanism, leaving the side-lasting mechanisms to be released automatically by power through means hereinafter described for that purpose.

There is further provided means for preventing the lever arm 648 from being caught

and held by the latch arm 698 in that outward movement of the side-lasting mechanisms which occurs after their first operation on the shoe at the shank and prior to their positioning movement toward the toe end of the shoe. For this purpose the bar 80 is provided with a notch in which it is engaged by a tooth formed on the upper end of a lever 704 pivoted on the bracket 81, this lever having thereon a roll 706 in engagement with the periphery of the cam wheel 666. On the periphery of this wheel is secured a cam 708 which engages the roll 706 at that time in the cycle when the arm 648 is lifted to swing the side-lasting mechanisms outwardly from the shank portion of the shoe, the cam acting on the lever 704 at that time to force the bar 80 inwardly and thus to hold the arm 698 in a position to prevent it from catching the arm 648. A spring 710 acts on the lever 704 to hold the roll 706 against the cam wheel 666 and also to return the bar 80 to its initial position. There is also secured on the periphery of the wheel 666 another cam 712 which is arranged to engage the roll 706 at the beginning of the cycle of the machine, so that if the opposite side-lasting mechanisms have not been released by the operator through movement of the plunger 72 before starting the machine they will be released automatically at the beginning of the cycle.

For moving the opposite side-lasting mechanisms from their first operating position to their second operating position, the rods 598 which carry the casing 596 and the parts associated therewith are connected at their outer ends by links 714 to arms 716 (Figs. 4 and 8) which are connected by a hub 718 fast on a rock shaft 720 mounted in bearings in the frame, and a spring 722 connected at one end to the hub 718 and at its other end to the frame acts when permitted to swing the arms 716 inwardly and thus to advance the side-lasting mechanisms. In this movement the casings 596 are carried into engagement with rolls 724 (Figs. 2 and 15) mounted on the slide 232 of the toe-lasting mechanism, so that the side-lasting mechanisms are positioned by the toe-lasting mechanism in proper relation thereto for their second operation on the shoe. It will be understood that in this advancing movement of the side-lasting mechanisms the toggle arms 642 slide along the rod 644. The rods 598 are held in their initial positions against the resistance of the spring 722 by a latch arm 726 pivoted on the frame and arranged to engage a lug 728 on one of the links 714, as illustrated in Fig. 8. For lifting this latch arm to release the side-lasting mechanisms there are provided connections to the heel-wiper-operating means which act to effect such release at the time when the heel wipers have partially completed their operative movement. These connections comprise

a link 730 connected at its lower end to the latch arm and provided at its upper end with a slot 732 in which is mounted a pin 734 carried by the hub portion of the arm 594 which 5 operates the heel wipers. It will thus be seen that the slot 732 provides for lost-motion of the pin 734 such that the latch arm 726 is not lifted until the heel wipers have partially completed their operation on the shoe. In 10 order to impart to the side-lasting mechanisms their return movement lengthwise of the shoe, there is fast on the rock shaft 720 a bell-crank lever having an arm 736 (Fig. 8) arranged to engage the end of an adjusting screw 738 carried by one of the arms 716, the bell-crank lever having another arm 740 which is forked (Fig. 4) to embrace the vertical rod 498 previously described as means for operating the heel presser foot 382, the 15 arm 740 being so arranged that in the upward movement of the rod 498 in the return of the parts of the machine to starting positions it is engaged and lifted by the member 510 in which the lower end of the rod 498 is swiveled. 20 It will be understood that at this time the latch arm 726 will have been returned into position to catch and hold the lug 728. The screw 738 assists in determining the correct position of adjustment of the bell-crank levers 736, 740 for the required amount of movement of the rods 598.

The machine is further provided with means which differs in some respect from that disclosed in Letters Patent No. 1,775, 25 225 for engaging the insole at the shank portion of the shoe and for thus holding the opposite side portions of the insole close to the bottom of the last until the side-lasting mechanisms have begun to lay the margin of the 30 upper over the insole in that location. For this purpose there is pivotally mounted on lugs 742 (Figs. 9 and 10) formed on the casting 502 previously described as secured to the movable carrier 496, a hub 744 having 35 thereon an arm 746 which carries a pair of insole-engaging members 748 arranged to engage the insole at the opposite sides of its shank portion. The members 748 are supported on a holder 749 pivoted at 750 (Fig. 40 8) on the arm 746 for limited tipping movement, and are pivoted at 751 on the holder for swinging movements laterally of the shoe toward or from each other, the members being normally held apart by a spring 752 (Fig. 11) 45 which extends through a recess in the holder 749. By swinging movement of the arm 746 the members 748 are carried either downwardly into engagement with the insole or upwardly away from the shoe. For controlling the arm 746 the hub 744 is provided with a crank arm 754 connected by a link 756 to a crank arm 758 (Fig. 8) fast on a rock shaft 760 mounted in the carrier 496. The rock shaft 760 carries a gear sector 762 engaged 50 by a rack bar 764 vertically movable in the

carrier 496 and having at its lower end a ball-and-socket connection with a link 766 (Figs. 4 and 8), this link at its lower end being pivotally connected to a coupling member 768 which is swiveled in one end of a lever 770 pivotally mounted at 772 on the frame of the machine. Universal connections are thus provided between the link 766 and the rack bar 764 at one end and the lever 770 at the other end, so as not to interfere with the swinging of the carrier 496. At its outer end the lever 770 is connected to the upper end of a rod 774 the lower end of which is yieldingly connected to a lever 776 mounted to turn on a rock shaft 778 (Fig. 1) mounted in bearings in the frame of the machine. For yieldingly connecting the rod 774 to the lever 776, there is pivoted to the lever a tubular member 780 having threaded in its upper end a thimble 782 through which the rod 774 is 55 slideable, and between this thimble and a head 784 on the lower end of the rod is a spring 786. For controlling the lever 776 there is provided a cam 788 carried by the cam shaft 132 and arranged to engage a roll 790 on the lever, the lever being further controlled by a spring 792 which acts to lift it when permitted by the cam.

The insole-engaging members 748 are, however, not moved into operative position directly by the cam 788, but in response to the downward movement of the presser foot carrier 496. It will be evident that in its movement either upwardly or downwardly this carrier tends to move the rack bar 764 with it, and that in so far as there is resistance to such movement of the rack bar the tendency is to turn the gear sector 762. The result is that when the carrier 496 is in its initial upper position the arm 746 is tipped upwardly with the members 748 in engagement with a pad 793 on the casting 502 by reason of the action of the rack bar 764 on the gear sector 762, and the rack bar also is raised to such an extent that through the lever 770 and the rod 774 the lever 776 is maintained against the tension of its spring 792 in a position in which the roll 790 is below the path of movement of the cam 788, the head 784 of the rod engaging the lower end of the tubular member 780. The cam arrives in a position over the roll at a time in the cycle before the carrier 496 has received much downward movement, and in consequence the cam acts as an abutment in engagement with the roll to limit such upward movement of the lever 776 as results from the downward movement of the carrier and the rack bar.

The rack bar 764 thus becomes temporarily stationary, so that further downward movement of the carrier 496 results in swinging the insole-engaging members 748 downwardly into engagement with the insole, the spring 786 yielding in response to downward movement of the rack bar with the carrier 496

after these members have engaged the insole. When the cam 788 has turned far enough to release the roll 790, the spring 792 lifts the lever 776 and thereby operates the rack bar 764 to swing the insole-engaging members 748 upwardly away from the shoe. In the upward movement of the carrier 496 which occurs thereafter in the return of the parts to starting positions, the insole-engaging members are maintained in their idle position against the pad 793 and the rack bar 764 is lifted with the carrier to move the lever 776 downwardly to its initial position. It will be understood that the cam 788 is so arranged as to maintain the insole-engaging members in operative position until the opposite side-lasting mechanisms have begun to lay the upper inwardly over the insole, the members being forced inwardly against the resistance of their spring 752 in response to the inward movement of the lasting fingers 604 and the straps 602. It will be further understood that the members 748 are so arranged that they engage the inner face of the margin of the upper to assist the straps in laying the margin tightly and evenly over the insole.

The machine is also provided with means which is in many respects similar to that disclosed in another copending application, Serial No. 250,885 filed on January 31, 1928, for removing the shoe from the machine after the lasting operations have been completed and after the different lasting mechanisms have moved away from the shoe. For this purpose there is mounted in bearings in the frame a rock-shaft 794 on which is secured a shoe carrying arm 796, the rock-shaft extending horizontally lengthwise of the shoe so that the arm is movable in a vertical plane extending laterally of the shoe. As illustrated particularly in Fig. 25, the arm 796 has thereon mechanism for gripping the heel-end portion of the shoe on the shoe support when the arm is in one position and for releasing the shoe after it has been carried to a different position. A hollow plunger 798 is mounted for sliding movement lengthwise in a block 800 which is fast on the arm 796, and fast on one end of the plunger 50 is a cross-bar 802 on which is pivotally mounted a plate 804 for engaging the bottom face of the heel end of the shoe. A spring 806 which is mounted in the plunger 798 with one end abutting against a bracket 808 secured on the block 800 holds the plunger initially in a position determined by a lug 810 which projects from the plunger into a slot in the block, and the spring is yieldable in response to continued movement of the arm 796 after the plate 804 has been carried into engagement with the shoe. Pivotally mounted on studs 812 on the opposite ends of the cross-bar 802 are shoe-gripping arms 814 and 816 each comprising two members 75 which are arranged to swing as a unit and

also to swing relatively to each other to a limited extent. Between each member 814 and the adjacent member 816 is a spring 818 which tends to impart to these members relative swinging movement about the stud 812, such relative movement being limited by interengagement of these members at 820. Each of the members 816 carries at its outer end a shoe-gripping or clamping member 822 preferably faced with leather, this member being swiveled on a pivot stud 824 which is pivoted at 826 on the member 816. Each of the members 814 is provided with a roll 828 for engagement with a wedge-face 830 on the block 800, and a spring 832 tends to swing these members toward each other and thus to hold the clamping members 822 in widely separated relation when permitted by the wedge-faces 830. It will be understood that as the arm 796 continues its swinging movement after the plate 804 has engaged the shoe, the wedge-faces 830 act to swing the clamping members 822 into engagement with the sides of the heel end of the shoe, the springs 818 then being compressed to some extent by movement of the members 814 relatively to the members 816 so that the shoe is gripped yieldingly. As this gripping action takes place the block 800 slides downwardly along the plunger 798, compressing the spring 806, and at the end of the swinging movement of the arm 796 the plunger is locked by a pawl 834 pivoted in a recess in the block 800 and arranged to engage ratchet teeth 836 formed on the side of the plunger 798. For controlling the pawl 834 there is provided a rod 838 slidably mounted in the block 800 and connected at one end to a finger 840 on the pawl, a spring 842 being arranged to move the rod in the direction to force the pawl against the plunger 798. The shoe-gripping members 822 are thus retained in gripping position when the arm 796 receives its reverse swinging movement so that the shoe is lifted from the shoe support and is carried by the arm to the position in which it is released.

In moving from the position in which it grips the shoe to the position in which it releases the shoe the arm 796 swings through an arc of approximately 180°, so that when the shoe is released it is positioned bottom downward. Partially enclosing the path of movement of the shoe-carrying means is a casing 844. For releasing the shoe at the end of the swinging movement of the arm, there is pivoted at 846 on the bracket 808 an arm 848 having a projection 850 for engaging the end of the rod 838 and also having thereon a roll 852. By the movement of the arm 796 the roll 852 (Fig. 7) is carried into engagement with an abutment member 854 mounted in the casing 844, this member acting as a stop which causes the arm 848 to swing about the pivot 846 and thus to act on the rod 838.

- to withdraw the pawl 834 from the ratchet teeth 836. The plunger 798 is thus released to the action of its spring 806, which results in separation of the shoe clamping members 822 and release of the shoe. The shoe when thus released is received by a chute 856, (Fig. 6), and in the machine herein shown is directed thereby to a conveyor belt 858 hereinafter more particularly referred to.
- 10 For imparting to the arm 796 its oscillating movements, in the machine herein shown there is fast on the rock-shaft 794 (Fig. 4) a pinion 860 engaged by a rack bar 862 movable in a bearing in the frame and connected 15 by a link 864 to an arm 866 fast on the previously mentioned rock-shaft 142. The link 864 is provided with a turn-buckle 868 for the purpose of adjustment hereinafter referred to. Also fast on the rock-shaft 142 20 (Fig. 7) is a gear sector 870 which is engaged by another gear sector 872 formed on one end of an arm 874 which is pivotally mounted on the previously mentioned shaft 778. The arm 874 carries a roll 876 engaged by a path cam 878 formed in one side of the cam wheel 666. It will thus be seen that operative movement is imparted to the shoe-removing mechanism automatically in time relation to the other operations of the machine.
- 25 Initially the mechanism is in the position illustrated in Figs. 6 and 7, and in operation it swings toward the front of the machine and downwardly into position to grip the shoe and then returns with the shoe to its initial 30 position where the shoe is released.
- The turn-buckle 868 permits an adjustment such as to vary the limit of movement of the arm 796 toward the shoe, which is desirable in operating on shoes of different 35 sizes in order that the shoe-gripping means shall grip each shoe with sufficient pressure. It will be evident that such an adjustment also varies the limit of movement of the arm in the opposite direction. In order to insure 40 that under such varying conditions the pawl 834 will always be so controlled as to effect the release of the shoe without necessity of adjustment, the previously mentioned abutment 854 in the machine herein shown is provided with a face 880 (Fig. 7) for engaging the roll 852, this face being inclined in relation to the path of movement of the roll and so arranged as to engage the roll early enough in the movement of the arm 796 to insure 45 the release of the shoe regardless of such adjustment as may be made for different sizes of shoes. Another face 882 on the member 854 is arranged in angular relation to the face 880 and in such relation to the path of movement of the roll 852 as to permit further movement of the shoe-carrying mechanism after the release of the shoe without any substantial effect upon the pawl 834. That is, the face 882 acts simply to maintain 50 the pawl in releasing position in such fur- ther movement of the shoe-carrying mechanism as may occur under some conditions of adjustment after the pawl has been moved to that position by the action of the face 880.
- The machine herein shown is operated by 55 an electric motor 884 (Figs. 2 and 6) connected by a chain belt 886 to a shaft 888 (Fig. 26) mounted in bearings on the base of the machine and carrying a worm 890 in driving engagement with a worm gear 892 mounted on the cam shaft 132 in such manner as to turn at times idly on the cam shaft. The worm gear 892 is thus driven continuously, and it is so formed as to serve as one member of a clutch cooperating with another member 894 which is keyed to the cam shaft 132. For connecting the two clutch members to drive the machine, there is mounted within a recess in one side of the gear 892 an annular member 896 provided with a 60 series of teeth 898, and mounted for oscillatory movement in a bearing sleeve 900 in the member 894 is a cylindrical member 902 which is cut away at one end to provide a projection 904 extending into the recess in 65 the gear 892 and having a flat surface facing the series of teeth 898. It will thus be understood that when the member 902 is in one position the gear 892 will rotate idly, and that when the member is turned to a different position one edge of its projection 904 will catch on one of the teeth 898 and thus connect the gear wheel to the other clutch member 894. For controlling the member 902 it carries a pin 906 which projects outwardly through a slot 908 in the sleeve 900 and the member 894, and secured on one end of the member 902 is an arm 910 connected by a spring 912 to the member 894. It will be 70 seen that the spring thus tends to turn the member 902 into position to connect the two parts of the clutch. For holding the member in idle position prior to the starting of the machine, there is pivotally mounted on one end of the shaft 516 an arm 914 which has on its outer end a plate 916 arranged to engage the pin 906, as illustrated in Fig. 26. Upward movement of the arm 914 releases the pin and permits the spring 912 to act on 75 the member 902 to connect the two parts of the clutch, whereupon the machine begins its cycle of operations, as illustrated in Fig. 6. There is further provided means for locking the member 902 in operative position, comprising a finger 918 pivoted on one side of the clutch member 894 and having in one end a notch 920 which receives a projection 922 on the arm 910 when the member 902 is in operative position. It will be understood that the arm 910 and the finger 918 are not in the same plane perpendicular to the shaft 132, so that the projection 922 slides along one surface of the finger 918 until it 80 enters the notch 920. The finger 918 is 85

held in contact with the projection 922 by a spring 924.

The machine herein shown is provided with simple and convenient means for controlling the clutch to start the machine by connecting the arm 914 to the arm 384 which carries the toe presser-foot 380, and, as hereinbefore described, is swung forwardly by the operator from an idle position to a position in which the presser-foot is over the toe end of the shoe. As previously described, this swinging movement of the arm 384 is accompanied by lengthwise movement of the rod 408 (Figs. 6 and 18) outwardly through the bearing member 414, and for the purpose in view the end of this is arranged to engage a screw 926 mounted in one arm 928 of a bell-crank lever pivoted on a bracket on the frame of the machine, the other arm 930 of this lever being connected by a link 932 to the arm 914. For connecting the link to the arm 914 there is secured on the lower end of the link a hook 934 arranged to engage a plate 936 carried by the arm. It will thus be seen that the arm 914 is lifted to release the pin 906 in response to the forward swinging movement of the toe presser-foot arm 384. In order that the machine shall be stopped automatically at the end of its cycle, a slot 938 is provided in the plate 936 through which the hook 934 extends, so that the hook may be disconnected from the plate by moving it toward the left from the position indicated in Fig. 26, a spring 940 being provided against the resistance of which such movement is effected. For thus moving the hook 934 to release the arm 914 and permit the latter to return the plate 916 into engagement with the periphery of the member 894 in the path of movement of the pin 906, there is secured on the member 894 a block 942 which arrives in position to engage the lower end portion of the hook shortly after the starting of the machine. It will be understood that eventually the hook 934 is returned into position to connect again with the arm 914 by the return movement of the arm 384 near the end of the cycle. In order that the plate 916 may act on the pin 906 to stop the machine, it is necessary to release the arm 910 from the finger 918, and for this purpose there is secured on one edge of the plate a lug 944 in position to engage the finger 918 and release the arm 910 at the proper time.

It will be understood that before the shoe-removing mechanism is moved into position to grip the shoe the various lasting instrumentalities are withdrawn to their idle positions to free the shoe and provide room for its removal. In order to guard against such damage as might result in case the slide 62, which carries the heel band and heel wipers, should not be properly returned and held by the catch 66 in the manner hereinbefore de-

scribed, there is provided means for automatically stopping the machine at a point in the cycle immediately before the shoe-removing mechanism arrives in position to grip the shoe if the slide 62 at that time in the cycle is not in its idle position. For this purpose there is pivotally mounted on the rod 592 (Figs. 3 and 8) a bell-crank lever having one arm 946 in the path of movement of the slide 62 and another arm 948 connected by a link 950 to a bell-crank lever 952 pivoted at the base of the machine, this lever being connected by a link 954 to an arm 956 fast on a hub 958 pivotally mounted on a bracket 959 at the left hand end of the machine (Fig. 6). The hub 958 also has thereon another arm 960 which carries a screw 962 (Fig. 3) arranged to engage the lower face of one arm 964 of a bell-crank lever pivoted at 966 on the bracket 959, this lever having another arm 968 which extends into such relation to the clutch as to act as a stop in engagement with the pin 906 when the arm 968 is in one position, a spring 970 being provided to swing the arm to that position when permitted by the arm 960. It will thus be seen that at any time when the slide 62 of the heel-lasting mechanism is in the position illustrated, with the heel band and heel wipers adacent to the shoe, the arm 968 is in such position as to stop the machine at the required point in the cycle to prevent interference between the shoe-removing mechanism and the heel lasting mechanism, and that when the slide 62 is returned to its idle position by the catch 66, as it normally is, near the end of the cycle of the machine, the slide by engagement with the arm 946 acts through the connections described to swing the arm 968 out of operative position, so that the machine will not be stopped until the end of the cycle. In order that the machine may be stopped by the action of the arm 968, if required, there is mounted in the path of movement of the locking finger 918 a lug 972 which acts to release the arm 910 at the proper time. It will be evident that regardless of the position of the arm 968, the lug 972 will always act on the finger 918, but under normal conditions such release of the arm 910 as is thereby effected is only momentary and involves no substantial liability of slipping of the member 902 of the clutch out of its operative position. It will also be understood that in case the machine is stopped by the action of the arm 968, all that is necessary in order to start it again is to move the slide 62 of the heel-lasting mechanism to its idle position by depression of the treadle 140, since that will result in release of the pin 906 by the arm 968 so that the parts of the clutch will again be connected together.

As a safeguard against possible injury to the operator or to a person unfamiliar with the operation of the machine, there is provided means for preventing such swinging

movement of the presser foot arm 384 as to trip the clutch unless the slide 62 of the heel-lasting mechanism has been previously released by movement of the plunger 72. For this purpose a hook 974 (Fig. 6) formed on one end of a lever 976 pivoted at 978 on the bracket 959 is arranged to engage a pin 980 on the lower end of a lever 982 which is pivotally mounted on one end of the shaft 124 and is connected by a link 984 to an arm 986 integral with or secured to the clutch-tripping arm 914. When the parts are in their initial positions the hook 974 is in position to catch on the pin 980 and thus to prevent lifting of the arm 914, and since the hook 934 on the link 932 is connected to the arm 914, movement of the lever arm 928 also is prevented, so that the screw 926 carried by this arm acts as an abutment in engagement with the end of the rod 408 to prevent forward swinging movement of the presser foot arm 384 from its idle position. The lever 976 is so arranged as to be controlled by the arm 964 previously referred to as controlled by the slide 62 of the heel-lasting mechanism, the lever being provided with a screw 988 arranged to be engaged by the upper face of the arm 964. It will be understood that when the slide 62 is in its initial idle position the arm 964 is in a raised position, so that it acts on the lever 976 to hold the hook 974 in position to catch on the pin 980. When the slide 62 is released in response to the movement of the plunger 72 the arm 964 is lowered, as previously described, and a spring 990 then acts on the lever 976 to lift the hook and release the pin 980 so that the machine may be started by the swinging of the arm 384. When the clutch-tripping arm 914 is released by the hook 934, the pin 980 is returned to its first position, so that when the lever 976 is returned by the action of the slide 62 at the end of the cycle the hook 974 is moved into locking relation to the pin. This mechanism affords practical insurance against starting of the machine by a person unfamiliar with its operation and also against tripping of the clutch at a time when the motor 884 is not running, so that danger is avoided of possible injury to the operator in starting the motor in ignorance of the fact that the clutch had been tripped. By reference to Fig. 6 it will be seen that a spring 992 connected to the arm 986 assists in returning the clutch-controlling arm 914 and the parts connected therewith to operative position. It will be evident that the plate 916 on the arm 914 not only serves to swing the pin 906 to its idle position, but also serves as a stop in engagement with the pin to prevent movement of the parts of the machine beyond a predetermined point when the clutch is released. In order to guard against the possibility of undue strain on the parts in thus stopping the machine, there is provided a brake (Figs. 1 and 5) which acts frictionally in engagement with the periphery of the cam wheel 666. This brake comprises a brake shoe 994 arranged to engage the cam wheel 666 and pivotally mounted on a crank arm 996 which is fast on a rock shaft 998 mounted in bearings in a bracket 1000 on the base of the machine. For controlling the shaft 998 there is fast thereon a crank arm 1002 (Fig. 5) on which is pivoted at 1004 a lever 1006 having on one end a roll 1008 for engaging the periphery of the cam wheel 130 and having at its other end a spring plunger 1010 arranged to bear on the hub of the crank arm 1002. For pressing the brake shoe 994 on the cam wheel 666 at the end of the cycle there is provided on the periphery of the cam wheel 130 a projection 1016 which engages the roll 1008 at the proper time and thereby acts through the connections including the spring plunger 1010 to apply the brake yieldingly. It will be understood that the brake shoe does not act with sufficient pressure to interfere with the starting of the machine, and that immediately after the machine is started the projection 1016 releases the lever 1006.

It is sometimes advantageous to operate the machine slowly by hand in order to observe the action of different parts or for other reasons, and to permit this conveniently to be done there is mounted on one end of the shaft 888 (Figs. 6 and 26) a sprocket wheel 1018 the hub of which is provided with teeth 1020 arranged to engage a pin 1022 which is fixed in the shaft, the sprocket wheel being movable lengthwise of the shaft either into or out of position for the teeth to engage the pin. The sprocket wheel 1018 is connected by a chain 1024 to a smaller sprocket wheel 1026 fast on a shaft 1028 rotatably mounted in a bearing in a bracket on the frame, and on one end of this shaft is a pin 1030 arranged to be engaged by teeth formed on the hub of a hand crank 1032 which may be detachably mounted on the shaft 1028. For pushing the sprocket wheel 1018 into position for its teeth to engage the pin 1022 there is provided a spring-controlled plunger 1034 adapted to be operated by the operator's foot. It will thus be understood that when it is desired to operate the machine by hand, the motor 884 being idle, the operator pushes the sprocket wheel 1018 into operative position by means of the plunger 1034 and applies the crank 1032 to the shaft 1028 and operates it to impart the required movement to the machine, the clutch having been previously tripped. Normally the sprocket wheel 1018 is maintained by the chain 1024 in a position in which it is disconnected from the pin 1022.

The conveyor belt 858 previously referred to, only a portion of which is shown, is operated through worm gearing 1036 (Fig. 6) 130

from a shaft 1038 which is driven through sprocket wheels and a chain 1040 by a shaft 1042 (Fig. 26), this shaft having on one end a bevel-pinion 1044 operated by a bevel-gear 1046 secured to one side of the continuously running gear wheel 892. It will thus be seen that the conveyor belt is operated from the same driving shaft 888 as the other power-operated parts of the machine, so that the belt 10 is always running when the rest of the machine is in operation. This arrangement is especially desirable since it insures that the shoes will be carried away from the vicinity of the shoe-removing mechanism, so that 15 there will be no danger of interference with the operation of this mechanism by an accumulation of shoes in the location where the shoes are released by the mechanism.

In the use of the machine the operator 20 takes a last with an upper mounted thereon and mounts the last on the spindle 30, and then while holding the upper pulled closely around the heel end of the last by engaging its forepart with one hand, he presses on the 25 pad 74 of the plunger 72 and thereby releases the slide 62, which supports the heel band and the heel wipers, to the action of the spring 70, so that the heel band and wipers are advanced toward the shoe and the heel 30 band is applied in clamping relation to the heel end of the upper. In response to the forward movement of the slide 62 the side-clamping members 206 are swung inwardly into clamping relation to the upper at the 35 sides of the shank by the action of the springs 220. The operator then by his fingers pulls the upper upwardly at the opposite sides of the shank, and by further movement of the plunger 72 releases the side-lasting mechanisms, so that they are moved inwardly by the spring 636 into clamping relation to the upper at the sides of the shoe, portions of the lasting straps 602 overlapping the clamping members 206. Thereafter the operator places 40 an insole upon the bottom of the last in proper relation to the last and to the margin of the heel and shank portions of the upper. 45

In response to the above described forward movement of the slide 62 the hook 974 (Fig. 50 6) is lifted to permit forward swinging movement of the toe presser foot arm 384. While holding the insole in proper position with his fingers the operator next takes hold of the handle 416 and swings the arm 384 forwardly 55 to bring the toe presser foot 380 into position over the shoe, and by that movement the clutch is actuated to start the machine. The arm 384 and the heel presser foot carrier 496 are then moved downwardly by power, the 60 carrier 496 being swung from its idle position to operative position over the shoe in the first part of its downward movement. In the downward movement of the carrier 496 the members 542 and 546 act to depress the heel 65 wipers against the resistance of their sup-

porting plungers and to position them in a relation to the heel end of the shoe bottom determined by engagement of the heel presser foot 382 with the insole; and also in response to the downward movement of the carrier the shank holddown members 748 are swung into engagement with the insole. As the toe presser foot arm 384 is moved downwardly, the member 452 on the arm is carried into engagement with the insole and the spring 75 464 then yields to permit the toe presser foot 380 to seat itself upon the insole.

In the latter part of the downward movement of the heel presser foot and the toe presser foot the shoe is depressed, together 80 with its supporting slide 34, the heel band, the heel wipers and the side clamps 206. In this downward movement of the shoe the side-lasting straps 602 act to wipe the upper 85 in the shank upwardly toward the edge of the insole, the upper being held from objectionable displacement during this upwiping action by the clamp members 206. Also in this downward movement of the shoe the member 452 at the toe end of the insole receives a forward movement in response to the action of the abutment member 474 on the rack bar 470, to insure that the insole around the toe will be positioned smoothly and closely against the bottom of the last. The toe rest 266 is at the same time forced downwardly by the shoe and is moved forwardly by the action of the cam 280 to tighten the upper lengthwise of the last simultaneously with the upwiping of the upper around the toe by the toe band 250. A further operation performed in response to the downward movement of the shoe is the upwiping of the upper at the ends of the toe band 250 by the 90 action of the straps 330 controlled by the toe wipers. 95

Substantially at the end of the downward movement of the shoe the side-lasting mechanisms are operated to lay the margin of the upper over the insole and to press it down upon the insole at the shank, the holdown members 748 being released and swung upwardly away from the shoe shortly after the side-lasting strips begin their overlaying action upon the upper. The side-lasting mechanisms are then swung outwardly away from the shoe and the toe and heel wipers are operated to lay the margin of the upper inwardly over the insole. In the operative movement of the toe wiper plates 296 and 298 the straps 330, which extend upwardly across the edge of the shoe bottom and are operated by the plates 298, are bent inwardly over the shoe bottom to lay the upper over the insole 100 in locations at the ends of the toe wipers and to insure that the insole in those locations will be pressed down upon the last bottom without danger of being displaced by the wiping action of the wipers. As the toe wipers move inwardly over the bottom of the 105 110 115 120 125 130

shoe the member 452 acts as a retarder to assist the wipers in wiping the margin of the upper tightly and evenly over the insole, and finally this member is lifted by the wedging 5 action of the wipers to permit the wipers to move inwardly beneath it and thus to lay the upper flat upon the insole. Near the end of the closing movements of the toe and heel wipers the toe presser foot and the heel presser 10 foot are raised a short distance to permit the toe portion of the shoe to be forced upwardly against the toe wipers with greater pressure by the action mainly of the springs 274 and 290 under the toe rest. At the same 15 time the shoe supporting slide 34 is raised by its spring 36, but the relation between the shoe and the heel wipers is not changed since the heel presser foot 382 remains in engagement with the shoe and the heel wipers accompany 20 the shoe in its upward movement.

Near the end of the operative movements of the toe and heel wipers the opposite side-lasting mechanisms are released by the latch 726 and are advanced by the spring 722 to 25 their second operating position near the toe wipers. These side-lasting mechanisms are then moved inwardly again into engagement with the sides of the shoe and are operated to lay the margin of the upper over the insole 30 between the portion of the shoe where they first operated and the portion operated upon by the toe wipers and the straps 330. As the side-lasting mechanisms engage the sides of the shoe in this second operation the 35 shoe is again depressed somewhat by the action of the toe and heel presser feet, which results in an upwiping of the upper by the straps 602 and also in relieving the pressure of the toe wipers on the shoe so that these 40 wipers may be withdrawn without danger of displacing the margin of the upper.

After the second operation of the side-lasting mechanisms on the shoe the different 45 lasting mechanisms are returned to their starting positions and the shoe is thus released to permit its removal. The shoe-removing device preferably begins to swing from its idle position toward the shoe before 50 the lasting mechanisms are moved away from the shoe, but it does not arrive in position to grip the shoe until the shoe has been entirely freed. As the plate 804 of the shoe-removing mechanism comes down on the heel 55 end portion of the shoe bottom it engages the margin of the heel end of the upper and presses it against the insole, thus affording further insurance that this portion of the upper will be pressed firmly into position to 60 adhere to the insole. The shoe-removing device automatically grips the shoe and carries it toward the rear of the machine where it is released bottom downward upon the chute 856 and slides then onto the conveyor belt 65 858. At the end of the cycle of operations the machine is automatically brought to a

stop by the release of the clutch and the application of the brake shoe 994.

Having described the invention what I claim as new and desire to secure by Letters Patent of the United States is:

1. In a machine of the class described, the combination with a shoe support, of lasting means comprising a plurality of flexible lasting straps, members arranged to act through said straps to lay the margin of the upper of a shoe on said support inwardly over the insole, means for moving said members inwardly over the bottom of the shoe, and means arranged to act independently of the straps to effect relative movement of said members and the shoe heightwise of the shoe to press the upper upon the insole prior to the completion of the inward movement of the members over the shoe and to increase the pressure progressively as the members are moved farther inwardly.

2. In a machine of the class described, the combination with a shoe support, of lasting means comprising a plurality of flexible lasting straps, members arranged to act through said straps to lay the margin of the upper of a shoe on said support inwardly over the insole, means for moving said members inwardly over the bottom of the shoe, and automatic yieldable means arranged to act independently of the straps to effect relative movement of said members and the shoe heightwise of the shoe to press the upper upon the insole early in the inward movement of the members over the shoe.

3. In a machine of the class described, the combination with a shoe support, of lasting means comprising a plurality of flexible lasting straps, members arranged to act through said straps to lay the margin of the upper of a shoe on said support inwardly over the insole, means for moving said members inwardly over the bottom of the shoe, and automatic means for imparting to said members independently of the straps early in their inward movement over the shoe movement heightwise of the shoe toward the bottom face of the insole into position to press the upper upon the insole.

4. In a machine of the class described, the combination with a shoe support, of lasting means comprising a plurality of flexible lasting straps, members arranged to act through said straps to lay the margin of the upper of a shoe on said support inwardly over the insole, means for moving said members inwardly over the bottom of the shoe, and automatic yieldable means for imparting to said members independently of the straps prior to the completion of their inward movement over the shoe movement heightwise of the shoe toward the bottom face of the insole to press the upper upon the insole and for increasing the pressure progressively as the members are moved farther inwardly.

5. In a machine of the class described, the combination with a shoe support, of lasting means comprising a plurality of flexible lasting straps, members arranged to act through said straps to lay the margin of the upper of a shoe on said support inwardly over the insole, said members being movable inwardly over the bottom of the shoe relatively to the straps, and means for imparting to said members independently of the straps early in their inward movement over the shoe movement heightwise of the shoe toward the bottom face of the insole into position to press the upper upon the insole.
- 15 6. In a machine of the class described, the combination with a shoe support, of lasting means comprising a plurality of flexible lasting straps, members arranged to act through said straps to lay the margin of the upper of a shoe on said support inwardly over the insole, means for moving said members inwardly over the bottom of the shoe, and means for imparting to said members early in their inward movement over the shoe movement heightwise of the shoe toward the bottom face of the insole to press the upper upon the insole including mechanism for substantially equalizing the pressures applied by the different members.
- 25 7. In a machine of the class described, the combination with a shoe support, of side-lasting means comprising a plurality of flexible lasting straps arranged to extend heightwise of a shoe on said support, means for pressing said straps against the lateral surface of the shoe, members arranged to act through said straps to lay the margin of the shoe upper inwardly over the insole, means for moving said members inwardly over the bottom of the shoe, and means for imparting to said members independently of the straps early in their inward movement over the shoe movement heightwise of the shoe toward the bottom face of the insole to
- 35 press the upper upon the insole and for increasing the pressure progressively as the members are moved farther inwardly.
8. In a machine of the class described, the combination with a shoe support, of side-lasting means comprising a plurality of flexible lasting straps arranged to engage the upper of a shoe on said support on its lateral surface and also to lay the margin of the upper inwardly over the insole, means for pressing portions of said straps against the lateral surface of the shoe and for holding said portions against movement while the straps are laying the upper over the insole, members yieldingly connected to said straps
- 45 and movable inwardly over the shoe bottom to cause the straps to lay the upper over the insole, and means for imparting to said members independently of the straps early in their inward movement over the shoe movement heightwise of the shoe toward the bottom face of the insole to press the upper upon the insole.
- 55 9. In a machine of the class described, the combination with a shoe support, of side-lasting mechanism comprising a plurality of flexible lasting straps arranged to effect substantially continuous engagement with the margin of the upper of a shoe on said support along a side of the shoe, members arranged to act through said straps to lay the margin of the upper inwardly over the insole, means for moving said members inwardly over the bottom of the shoe, and means for imparting to said members independently of the straps early in their inward movement over the shoe movement heightwise of the shoe toward the bottom face of the insole into position to press the upper upon the insole.
- 65 10. In a machine of the class described, the combination with a shoe support, of side-lasting means comprising a plurality of flexible lasting straps, members arranged to act through said straps to lay the margin of the upper of a shoe on said support inwardly over the insole, means for moving said members inwardly over the bottom of the shoe, said members being movable also heightwise of the shoe, means for rendering the straps effective to pull the members toward the bottom face of the insole as they are moved inwardly over the insole, and additional means for imparting to the members early in their inward movement over the shoe movement heightwise of the shoe toward the bottom face of the insole into position to press the upper upon the insole.
- 75 11. In a machine of the class described, the combination with a shoe support, of side-lasting means comprising a plurality of flexible lasting straps, members arranged to act through said straps to lay the margin of the upper of a shoe on said support inwardly over the insole, means for moving said members inwardly over the bottom of the shoe, said members being movable also heightwise of the shoe, yieldable connections between said members and the straps to render the straps effective to pull the members toward the bottom face of the insole while permitting movement of the members relatively to the straps as they are moved inwardly over the insole, and automatic means for imparting to the members independently of the straps early in their inward movement over the shoe movement toward the bottom face of the insole to press the upper upon the insole.
- 85 12. In a machine of the class described, the combination with a shoe support, of side-lasting means comprising a plurality of flexible lasting straps, members arranged to act through said straps to lay the margin of the upper of a shoe on said support inwardly over the insole, said members being mounted for swinging movement heightwise of the

shoe, means for moving the members inwardly over the bottom of the shoe, and means for imparting to said members independently of the straps early in their inward movement 5 over the shoe swinging movement to press the upper upon the insole.

13. In a machine of the class described, the combination with a shoe support, of side-lasting mechanism comprising a plurality of 10 flexible lasting straps, members arranged to act through said straps to lay the margin of the upper of a shoe on said support inwardly over the insole, said members being mounted for movement heightwise of the shoe, means 15 for moving the members inwardly over the bottom of the shoe, a lever arm movable progressively during the inward movement of said members, and means for moving the members heightwise of the shoe by that movement 20 of the lever arm to press the upper with increasing force upon the insole as the members are moved inwardly.

14. In a machine of the class described, the combination with a shoe support, of side-lasting mechanism comprising a plurality of flexible 25 lasting straps, members arranged to act through said straps to lay the margin of the upper of a shoe on said support inwardly over the insole, said members being mounted for swinging movement heightwise of the shoe, means for moving the members inwardly over the bottom of the shoe, a lever arm 30 movable progressively during the inward movement of said members, and yieldable means for swinging the members in response to that movement of the lever arm to press the upper with increasing force upon the insole as the members are moved inwardly.

15. In a machine of the class described, the combination with a shoe support, of side-lasting 40 means comprising a plurality of flexible lasting straps, members arranged to act through said straps to lay the margin of the upper of a shoe on said support inwardly over the insole, said members being mounted for swinging movements heightwise of the shoe, means for moving the members inwardly over the bottom of the shoe, yieldable means for so 45 positioning the members as to afford substantial clearance between them and the bottom face of the insole as they begin their inward movement, and means arranged to act independently of the straps to impart to the members early in their inward movement 50 swinging movement toward the bottom face of the insole to press the upper upon the insole.

16. In a machine of the class described, the combination with a shoe support, of side-lasting 60 means comprising a plurality of flexible lasting straps, lasting fingers connected to the different straps for laying the margin of the upper of a shoe on said support inwardly over the insole, said fingers being arranged to extend outwardly from the shoe and ful-

crum between their ends for swinging movements heightwise of the shoe, means for moving the fingers inwardly over the bottom of the shoe, and means arranged to act on the outer end portions of the fingers to impart thereto early in their inward movement over 70 the shoe swinging movement to press the upper upon the insole.

17. In a machine of the class described, the combination with a shoe support, of side-lasting mechanism comprising a plurality of flexible lasting straps, lasting fingers connected to the different straps for laying the margin of the upper of a shoe on said support inwardly over the insole, said fingers 75 being arranged to extend outwardly from the shoe and fulcrum between their ends for swinging movements heightwise of the shoe, means for moving the fingers inwardly over the bottom of the shoe, a plunger, an 80 equalizer on said plunger for engaging the outer end portions of the fingers to swing them, and means arranged to act on said plunger with progressively increasing force in the inward movement of the fingers over 85 the shoe to swing the fingers for pressing the upper upon the insole.

18. In a machine of the class described, the combination with a shoe support, of opposite side-lasting mechanisms comprising flexible 90 lasting straps, members arranged to act through said straps to lay the margin of the upper of a shoe on said support inwardly over the insole, said members being mounted for movements heightwise of the shoe, means 95 comprising toggle arms for imparting to said members movements inwardly over the bottom of the shoe, and means arranged to be operated by swinging movement of said toggle arms to impart to said members independently of the straps in their inward movement over the shoe gradual movement heightwise of the shoe to press the upper upon the insole.

19. In a machine of the class described, the combination with a shoe support, of opposite side-lasting mechanisms comprising flexible lasting straps, lasting fingers arranged to act through said straps to lay the margin of the upper of a shoe on said support inwardly over the insole, arms on which said fingers are fulcrum for swinging movements heightwise of the shoe, toggle members pivotally connected to said arms for operating them to move the fingers inwardly over the bottom of the shoe, and means arranged to be operated by swinging movement of said toggle members to subject said fingers in their inward movement to gradually increasing force tending to swing them in directions 115 to increase their pressure on the upper.

20. In a machine of the class described, the combination with a shoe support, of opposite side-lasting mechanisms comprising flexible lasting straps, lasting fingers arranged to act 120

- through said straps to lay the margin of the upper of a shoe on said support inwardly over the insole, supporting members mounted to swing laterally of the shoe and on which said fingers are fulcrumed between their ends for swinging movements heightwise of the shoe, toggle arms connected to said supporting members for moving them toward the shoe to carry the fingers inwardly over the bottom of the shoe, devices movable with said supporting members and arranged to engage the outer end portions of the fingers to swing the fingers heightwise of the shoe, and means for yieldingly operating said devices by swinging movement of said toggle arms to increase the pressure of the fingers on the upper progressively as they are moved inwardly over the shoe.
21. In a machine of the class described, the combination with a shoe support, of a flexible lasting strap, a member arranged to act through said strap to lay the margin of the upper of a shoe on said support inwardly over the insole and to press it upon the insole, means for moving said member inwardly over the bottom of the shoe, and automatic means for imparting to said member independently of the strap early in its inward movement over the shoe movement heightwise of the shoe to press the upper upon the insole.
22. In a machine of the class described, the combination with a shoe support, of a flexible lasting strap, a member arranged to act through said strap to lay the margin of the upper of a shoe on said support inwardly over the insole and to press it upon the insole, means for moving said member inwardly over the bottom of the shoe, and automatic means for imparting to said member independently of the strap prior to the completion of its inward movement over the shoe movement heightwise of the shoe to press the upper upon the insole and for gradually increasing the pressure as the member is moved farther inwardly.
23. In a machine of the class described, the combination with a shoe support, of a flexible lasting strap, a lasting finger connected at one end to said strap and arranged to act through the strap to lay the margin of the upper of a shoe on said support inwardly over the insole, said finger being mounted to swing heightwise of the shoe to press the upper upon the insole, means for moving the finger inwardly over the bottom of the shoe, and means arranged to act on the other end of said finger to swing it heightwise of the shoe early in its inward movement over the shoe to press the upper upon the insole.
24. In a machine of the class described, the combination with a shoe support, of a flexible lasting strap, a lasting finger arranged to act through said strap to lay the margin of the upper of a shoe on said support inwardly over the insole, said finger being mounted to move heightwise of the shoe to press the upper upon the insole, a spring through which to impart to the finger its pressing movement, means for moving the finger inwardly over the bottom of the shoe, and automatic means arranged to act progressively through said spring in the inward movement of the finger over the shoe to increase gradually the pressure of the finger on the upper.
25. In a machine of the class described, the combination with a shoe support, of a flexible lasting strap arranged to extend heightwise of a shoe on said support, means for pressing said strap against the shoe exteriorly of the shoe bottom, a member connected to said strap and movable inwardly over the bottom of the shoe to lay the margin of the shoe upper over the insole, said member being movable toward the bottom of the shoe in response to pull of the strap thereon, and means automatically operative in the inward movement of said member over the shoe to subject said member to gradually increasing force tending to move it in the direction in which it is pulled by the strap for increasing its pressure on the upper.
26. In a machine of the class described, the combination with a shoe support, of a flexible lasting strap, a member arranged to act through said strap to lay the margin of the upper of a shoe on said support inwardly over the insole and to press it upon the insole, said member being movable heightwise of the shoe, means for moving the member inwardly over the bottom of the shoe, a lever arm movable progressively in the inward movement of said member over the shoe, and means for moving the member heightwise of the shoe by that movement of the lever arm to press the upper with gradually increasing force upon the insole as the member is moved inwardly.
27. In a machine of the class described, the combination with a shoe support, of lasting mechanism comprising a plurality of lasting members movable inwardly over the bottom of a shoe on said support to lay the margin of the upper over the insole, said members being movable heightwise of the shoe to press the upper upon the insole and relatively movable also heightwise of the shoe to conform to the contour of the shoe bottom, means for moving said members inwardly over the bottom of the shoe, and means for imparting to said members early in their inward movement over the shoe while laying the upper over the insole movement heightwise of the shoe to press the upper upon the insole.
28. In a machine of the class described, the combination with a shoe support, of lasting mechanism comprising a plurality of lasting members movable inwardly over the bottom

- of a shoe on said support to lay the margin of the upper over the insole, said members being movable heightwise of the shoe to press the upper upon the insole and relatively movable 5 also heightwise of the shoe to conform to the contour of the shoe bottom, means for moving said members inwardly over the bottom of the shoe, and automatic means for imparting to said members prior to the completion 10 of their inward movement over the shoe movement heightwise of the shoe to press the upper upon the insole and for increasing the pressure progressively as the members are moved farther inwardly.
29. In a machine of the class described, the combination with a shoe support, of lasting mechanism comprising a plurality of lasting fingers arranged to extend outwardly from a shoe on said support with their ends toward 20 the shoe, means for moving said fingers lengthwise inwardly over the bottom of the shoe to lay the margin of the upper over the insole, the fingers being mounted for swinging movements heightwise of the 25 shoe to press the upper upon the insole, and means progressively movable in the inward movement of the fingers over the shoe to subject the upper to gradually increasing pressure by the swinging of the fingers.
30. In a machine of the class described, the combination with a shoe support, of lasting mechanism comprising a plurality of lasting fingers arranged to extend outwardly from a shoe on said support with their inner ends 35 toward the shoe, means for moving said fingers inwardly over the bottom of the shoe to lay the margin of the upper over the insole, the fingers being mounted for swinging movements heightwise of the shoe to 40 press the upper upon the insole, and means arranged to engage the outer end portions of the fingers to swing them into upper-pressing positions early in their inward movement over the shoe and to increase progressively their pressure on the upper in 45 their further inward movement.
31. In a machine of the class described, the combination with a shoe support, of lasting mechanism comprising a plurality of lasting fingers arranged to extend outwardly from a shoe on said support, means for moving said fingers lengthwise inwardly over the bottom of the shoe to lay the margin of the upper over the insole, the fingers 50 being mounted for swinging movements heightwise of the shoe to press the upper upon the insole, a device for substantially equalizing the pressures applied by the different fingers, a spring arranged to act on said device to apply the pressure, and a member for subjecting said spring to progressively increasing stress as the fingers are moved inwardly over the shoe.
32. In a machine of the class described, the combination with a shoe support, of op- 55
- posite side-lasting mechanisms comprising members movable inwardly over the bottom of a shoe on said support to lay the margin of the upper over the insole and movable also heightwise of the shoe, toggle arms for moving said members inwardly, and means operated by swinging movement of said toggle arms to move the members heightwise of the shoe in their inward movement over the shoe to subject the upper to gradually increasing pressure.
33. In a machine of the class described, the combination with a shoe support, of opposite side-lasting mechanisms comprising lasting fingers for laying the margin of the upper of a shoe on said support inwardly over the insole, arms on which said fingers are fulcrumed for swinging movements heightwise of the shoe, toggle members connected to said arms for moving them toward the shoe to force the fingers inwardly over the shoe bottom, and means arranged to be operated by swinging movement of said toggle members to swing the fingers toward the bottom of the shoe with gradually increasing pressure on the upper in their inward movement over the shoe.
34. In a machine of the class described, the combination with a shoe support, of opposite side-lasting mechanisms comprising lasting fingers for laying the margin of the upper of a shoe on said support inwardly over the insole, arms on which said fingers are fulcrumed for swinging movements heightwise of the shoe, toggle members connected to said arms for moving them toward the shoe to force the fingers inwardly over the shoe bottom, said toggle members being extended beyond their connections with the arms, and yieldable means operated by the extensions of said toggle members for swinging the fingers toward the bottom of the shoe with gradually increasing pressure on the upper in their inward movement over the shoe.
35. In a machine of the class described, the combination with means for shaping over a last the sides of an unlaced upper between its forepart and its heel end portion, of means for clamping against the last portions of the upper subject to strain in the operation of said upper-shaping means to prevent distortion of the upper in the upper-shaping operation.
36. In a machine of the class described, the combination with means for shaping over a last the sides of an unlaced upper between its forepart and its heel end portion, of means for clamping against the sides of the last in locations spaced substantially from the bottom of the last portions of the upper subject to strain in the operation of said upper-shaping means to prevent distortion of the upper in the upper-shaping operation.
37. In a machine of the class described,

the combination with means for wiping the sides of an unlaced upper heightwise of a last between its forepart and its heel end portion, of means for clamping against the sides of the last in locations spaced substantially from the bottom of the last portions of the upper subject to strain in the upwiping operation to prevent distortion of the upper in that operation while affording room for the action of the wiping means thereon.

38. In a machine of the class described, the combination with opposite side-lasting mechanisms comprising flexible lasting straps for working an unlaced upper heightwise of a last at the opposite sides of its shank portion, of means for clamping against the last portions of the upper subject to the strain applied by the straps to prevent distortion of the upper by the action of the straps.

39. In a machine of the class described, the combination with opposite side-lasting mechanisms for wiping the sides of an unlaced upper heightwise of a last between its toe and heel end portions, of means for clamping against the sides of the last portions of the upper subject to strain in the wiping operation, said clamping means being arranged to be overlapped by a portion of the wiping means.

40. In a machine of the class described, the combination with opposite side-lasting mechanisms comprising flexible lasting straps for wiping an unlaced upper heightwise of a last at the opposite sides of its shank portion and for laying its margin inwardly over an insole on the last, of clamping devices arranged to engage portions of the sides of the upper subject to strain in the upwiping operation in locations spaced substantially from the bottom of the last to prevent distortion of the upper by the action of said straps, said devices comprising thin metal fingers arranged to be overlapped by portions of the straps.

41. In a machine of the class described, the combination with means for wiping an upper heightwise of a last at the opposite sides of its shank portion, of means for clamping against the last in locations spaced substantially from the bottom of the last portions of the upper subject to strain in the upwiping operation.

42. In a machine of the class described, the combination with means for wiping an upper heightwise of a last, of a clamping member of thin spring metal arranged to clamp the upper against the last in a location at a substantial distance from the last bottom and to be overlapped by a portion of said wiping means.

43. In a machine of the class described, the combination with flexible lasting straps for wiping an upper heightwise of a last, of a plurality of fingers of thin spring metal arranged to clamp the upper against the last in locations spaced substantially from the bot-

tom of the last and to be overlapped by portions of the straps.

44. In a machine of the class described, the combination with opposite side-lasting mechanisms comprising flexible lasting straps arranged to operate at the shank portion of an upper to shape it over a last, of clamping devices comprising spring metal fingers arranged to clamp the upper against the sides of the last in locations where the upper is subject to strain in the side-lasting operation.

45. In a machine of the class described, the combination with a support for a shoe on a last, opposite side-lasting mechanisms constructed and arranged to wipe the upper of a shoe on said support heightwise of the last between its toe and heel end portions, and means for depressing the shoe and its support relatively to the side-lasting mechanisms to effect the upwiping operation, of means movable with the shoe support for clamping the upper against the sides of the last in locations where the upper is subject to strain in the upwiping operation.

46. In a machine of the class described, the combination with a support for a shoe on a last, opposite side-lasting mechanisms constructed and arranged to wipe the upper of a shoe on said support heightwise of the last between its toe and heel end portions, and means for depressing the shoe and its support relatively to the side-lasting mechanisms to effect the upwiping operation, of devices carried by the shoe support for clamping the upper against the sides of the last in locations where the upper is subject to strain in the upwiping operation, said devices being movable into and out of operative position about axes extending heightwise of the shoe.

47. In a machine of the class described, the combination with a support for a shoe on a last, opposite side-lasting mechanisms comprising flexible lasting straps arranged to wipe the upper of a shoe on said support heightwise of the last and to lay its margin inwardly over an insole on the last, and means for depressing the shoe and its support relatively to the straps to effect the upwiping operation, of devices carried by the shoe support for clamping the upper against the sides of the last prior to depression of the shoe, said devices being arranged to engage portions of the upper subject to strain in the upwiping operation in locations at a substantial distance from the bottom of the last.

48. In a machine of the class described, the combination with a support for a shoe and last, of end-lasting mechanism mounted for movement lengthwise of the shoe into operative relation to the shoe, and means controlled by said movement of the end-lasting mechanism for clamping the shoe upper against the sides of the last in locations between its toe and heel end portions.

49. In a machine of the class described, the

- combination with a support for a shoe and last, of end-lasting mechanism mounted for movement lengthwise of the shoe into operative relation to the shoe, devices for clamping the shoe upper against the sides of the last in locations between its toe and heel end portions, and means for moving said devices into clamping position in response to said movement of the end-lasting mechanism. 5. In a machine of the class described, the combination with a support for a shoe and last, of heel-lasting mechanism movable lengthwise of the shoe into operative relation to the shoe, and means controlled by the movement of the heel-lasting mechanism for clamping the shoe upper against the sides of the last forwardly of its heel end. 10. In a machine of the class described, the combination with a support for a shoe and last, of a heel band for clamping the shoe upper about the heel end of the last, a support for said heel band movable to carry it into clamping position, and devices controlled by the movement of said heel band support for clamping the upper against the sides of the last forwardly of its heel end. 15. In a machine of the class described, the combination with a support for a shoe and last, of heel-lasting mechanism movable forwardly into operative relation to the shoe, devices for clamping the shoe upper against the sides of the last forwardly of its heel end, and spring means operative in response to the forward movement of the heel-lasting mechanism to move said devices into clamping position. 20. In a machine of the class described, the combination with a support for a shoe and last, of heel-lasting mechanism movable forwardly into operative relation to the shoe, devices for clamping the shoe upper against the sides of the last forwardly of its heel end, said devices being mounted for swinging movements about axes extending heightwise of the shoe, and spring means arranged to be rendered operative by the forward movement of the heel-lasting mechanism to swing said devices into clamping position. 25. In a power-operated lasting machine, the combination with a support for a shoe and last, of heel-lasting mechanism movable lengthwise of the shoe into operative position in response to control of the operator prior to the starting of the power operation of the machine, and means controlled by the movement of said heel-lasting mechanism for clamping the shoe upper against the sides of the last forwardly of its heel end also prior to the starting of the machine. 30. In a power-operated lasting machine, the combination with a support for a shoe and last, of a heel band and a support therefor movable in response to control of the operator to carry the band into operative relation to the shoe prior to the starting of the power operation of the machine, devices for clamping the shoe upper against the sides of the last forwardly of its heel end, and spring means controlled by the movement of the heel band support for moving said devices into operative position also prior to the starting of the machine. 35. In a machine of the class described, the combination with a shoe support, of heel-lasting mechanism mounted for rectilinear movement lengthwise of a shoe on said support toward and from the heel end of the shoe, a spring for moving said mechanism toward the shoe, and a retaining device for holding said mechanism initially in a position away from the shoe and for releasing it to the action of said spring. 40. In a power-operated lasting machine, the combination with a shoe support, of heel-lasting mechanism mounted for rectilinear positioning movement lengthwise of a shoe on said support, and automatic means arranged to be controlled by the operator for imparting to said heel-lasting mechanism its positioning movement prior to the starting of the power operation of the machine. 45. In a power-operated lasting machine, the combination with a shoe support, of a slide mounted for movement lengthwise of a shoe on said support toward and from the heel end of the shoe, a device carried by said slide for clamping the upper about the heel end of the last, a spring for operating said slide to apply the clamping device to the shoe, and a retaining member arranged to be controlled by the operator to release the slide to the action of its spring prior to the starting of the power operation of the machine. 50. In a power-operated lasting machine, the combination with a shoe support, of heel-lasting mechanism mounted for movement lengthwise of a shoe on said support toward and from the heel end of the shoe, a spring for moving said mechanism toward the shoe, a latch arranged to be controlled by the operator for releasing said mechanism to the action of its spring prior to the starting of the power operation of the machine, and automatic means for operating said latch to return the mechanism to its initial position. 55. In a power-operated lasting machine, the combination with a shoe support, of heel-lasting mechanism mounted for positioning movement lengthwise of a shoe on said support, a spring for moving said mechanism toward the shoe, means arranged to be controlled by the operator for releasing said mechanism to the action of its spring prior to the starting of the power operation of the machine, and a device for returning said mechanism to its initial position at the will of the operator prior to the starting of the machine. 60. In a power-operated lasting machine, the combination with a shoe support, of heel-lasting mechanism mounted for positioning movement lengthwise of a shoe on said support, a spring for moving said mechanism toward the shoe, means arranged to be controlled by the operator for releasing said mechanism to the action of its spring prior to the starting of the power operation of the machine, and a device for returning said mechanism to its initial position at the will of the operator prior to the starting of the machine.

61. In a machine of the class described, the combination with a shoe support, of wipers for lasting an end of a shoe on said support, yieldable means against the resistance of which said wipers are mounted to tip both lengthwise and laterally of the shoe, and relatively adjustable members arranged to act against the resistance of said yieldable means in locations spaced lengthwise and laterally of the shoe to control the wipers in respect to such tipping movements. 70
62. In a machine of the class described, the combination with a shoe support, of wipers for lasting an end of a shoe on said support, yieldable means against the resistance of which said wipers are mounted to tip both lengthwise and laterally of the shoe, said means comprising a spring plunger positioned beyond the end of the shoe and other spring plungers spaced laterally of the shoe, and members arranged to act in locations substantially opposite the different spring plungers to control the wipers in respect to such tipping movements. 80
63. In a machine of the class described, the combination with a shoe support, of wipers for lasting an end of a shoe on said support, yieldable means against the resistance of which said wipers are mounted to tip both lengthwise and laterally of the shoe, members arranged to act in locations spaced laterally of the shoe to control the wipers in respect to lateral tipping movement, and another member arranged to act in a location spaced lengthwise of the shoe from said first-named members and to cooperate therewith to position the wipers in respect to lengthwise tipping movement, said last-named member being independently adjustable to determine 90 variably the position of the wipers. 95
64. In a machine of the class described, the combination with a shoe support, of wipers for lasting an end of a shoe on said support, yieldable means against the resistance of which said wipers are mounted to tip both lengthwise and laterally of the shoe, members arranged to act in locations spaced laterally of the shoe to control the wipers in respect to lateral tipping movement, said members being movable together about an axis extending lengthwise of the shoe under control of the shoe to adjust the wipers relatively to the shoe bottom, and another member arranged to act in a location spaced lengthwise of the shoe from said first-named members and adjustable relatively to said members to determine positively the position of the wipers in respect to lengthwise tipping movement. 105
65. In a machine of the class described, the combination with a shoe support, of end-lasting wiper mechanism yieldingly supported to permit it to be depressed relatively to a shoe on said support and including wipers so mounted as to permit them to be tipped 110 lengthwise and laterally of the shoe as said mechanism is depressed, and means for engaging said wiper mechanism in three separate locations to depress it and to position the wipers relatively to the shoe. 115
66. In a machine of the class described, the combination with a shoe support, of end-lasting wiper mechanism yieldingly supported to permit it to be depressed relatively to a shoe on said support and including wipers so mounted as to permit them to be tipped lengthwise and laterally of the shoe as said mechanism is depressed, and a device mounted independently of said wiper mechanism for movement into engagement with it in three separate locations to depress it and to position the wipers relatively to the shoe. 120
67. In a machine of the class described, the combination with a shoe support, of end-lasting wiper mechanism yieldingly supported to permit it to be depressed relatively to a shoe on said support and including wipers so mounted as to permit them to be tipped lengthwise and laterally of the shoe as said mechanism is depressed, members spaced laterally of the shoe for engaging the wipers to depress and position them relatively to the shoe, and another member for engaging the wiper mechanism in a location spaced lengthwise of the shoe from said first-named members and substantially midway between the opposite sides of said mechanism to assist in positioning the wipers. 125
68. In a machine of the class described, the combination with a shoe support, of end-lasting wipers, yieldable means against the resistance of which said wipers are movable heightwise of a shoe on said support to position them relatively to the shoe, means for imparting to the wipers such positioning movement, and a member for engaging the bottom of the shoe to limit such movement of the wipers in relation to the shoe, said member being adjustable to vary the relation thus determined between the wipers and the shoe. 130
69. In a machine of the class described, the combination with a shoe support, of end-lasting wipers, yieldable means against the resistance of which said wipers are depressible to position them relatively to a shoe on said support, a member movable to depress the wipers, and a presser foot carried by said member for engaging the bottom of the shoe to determine the relation of the wipers to the shoe, said presser foot being adjustable to vary that relation. 135
70. In a machine of the class described, the combination with a shoe support, of end-lasting wiper mechanism yieldingly supported to permit it to be depressed relatively to a shoe on said support to position it in proper relation to the shoe, and depressing means mounted for swinging movement about an axis extending heightwise of the shoe to a position over the wiper mechanism 140

and for movement heightwise of the shoe into engagement with said mechanism.

71. In a machine of the class described, the combination with a shoe support, of end-lasting wiper mechanism yieldingly supported to permit it to be depressed relatively to a shoe on said support to position it in proper relation to the shoe, a member having thereon means for engaging and depressing the wiper mechanism and also a presser-foot for engaging the bottom of the shoe to determine the relation of said mechanism to the shoe bottom, and means for swinging said member about an axis extending heightwise of the shoe to a position over the wiper mechanism and for moving it then heightwise of the shoe to depress said mechanism.

72. In a machine of the class described, the combination with a shoe support, of heel-lasting mechanism mounted for rectilinear positioning movement lengthwise of a shoe on said support and including wipers movable against yielding resistance heightwise of the shoe to position them in proper relation to the shoe, and means mounted for movement about an axis extending heightwise of the shoe to a position over the wipers and for movement heightwise of the shoe to impart to the wipers their positioning movement.

73. In a machine of the class described, the combination with a depressible shoe support, of heel-lasting mechanism mounted on said support for positioning movement toward the shoe, and a shoe depressor movable about an axis extending heightwise of the shoe to a position over the heel end of the shoe and movable then heightwise of the shoe to depress the shoe with its support and heel-lasting mechanism.

74. In a machine of the class described, the combination with a shoe support, of a toe presser foot and a heel presser foot each movable about an axis extending heightwise of a shoe on said support to a position over the shoe and movable then heightwise of the shoe into shoe-engaging position.

75. In a machine of the class described, the combination with a depressible shoe support, of a toe presser foot and a heel presser foot each movable about a substantially vertical axis to a position over a shoe on said support and movable then downwardly to depress the shoe.

76. In a power-operated lasting machine, the combination with a shoe support, of a toe presser foot and a heel presser foot each movable about an axis extending heightwise of a shoe on said support to a position over the shoe and movable then heightwise of the shoe into shoe-engaging position, manual means for swinging the toe presser foot into position over the shoe, and power means for imparting to the heel presser foot its swing-

ing movement and for moving both presser feet heightwise of the shoe.

77. In a machine of the class described, the combination with a support for a shoe and last, of lasting means including power-operated mechanism for laying the margin of the shoe upper inwardly over an insole on the last, and means comprising a toe presser foot and a heel presser foot both movable by power first into engagement with the bottom 70 of the shoe and then to depress the shoe relatively to the lasting means.

78. In a machine of the class described, the combination with a support for a shoe and last, of toe-lasting means comprising a toe band and power-operated toe wipers, and means movable by power first into engagement with the bottom of the shoe and then to depress the shoe relatively to the toe-lasting means to cause the toe band to unwipe 80 the upper prior to the power operation of the toe wipers.

79. In a machine of the class described, the combination with a support for a shoe and last, of toe-lasting means, heel-lasting means, and means for depressing the shoe and the heel-lasting means relatively to the toe-lasting means, said depressing means comprising mechanism movable by power first into engagement with the bottom of the shoe and 90 then to depress the shoe.

80. In a machine of the class described, the combination with a support for a shoe and last, of lasting mechanism, a presser foot movable by the operator to a position over the bottom of the shoe, and power means for moving said presser foot from that position first into engagement with the bottom 100 of the shoe and then to depress the shoe relatively to the lasting mechanism.

81. In a machine of the class described, the combination with a support for a shoe and last, of lasting mechanism, a toe presser foot and a heel presser foot arranged to engage the bottom of the shoe and to depress the shoe relatively to the lasting mechanism, the toe presser foot being movable by the operator to a position over the bottom of the shoe, and power means for moving the heel presser foot to a position over the bottom of the shoe and for moving both presser feet 110 into engagement with the shoe and to depress the shoe.

82. In a power-driven machine for operating on shoes, the combination with a shoe support, of a shoe-engaging member mounted for movement by the operator to position it in relation to a shoe on said support, and means operative in response to the positioning movement of said member to start the 120 power operation of the machine.

83. In a power-driven machine for operating on shoes, the combination with a shoe support, of a presser foot mounted for movement by the operator from an idle position 130

- to a position over the bottom of a shoe on said support, and means operative in response to said movement of the presser foot to start the power-operation of the machine.
84. In a power-driven machine for operating on shoes, the combination with a shoe support, of a power-operated member mounted for preliminary movement by the operator to position it in relation to a shoe on said support prior to its operation by power, and means operative in response to the preliminary movement of said member to start the power operation of the machine.
85. In a power-operated lasting machine, the combination with a shoe support and lasting mechanism, of a presser member arranged to engage the bottom of a shoe on said support and mounted for movement by the operator to position it in relation to the shoe, and means operative in response to the positioning movement of said member to start the power operation of the machine.
86. In a power-operated lasting machine, the combination with a shoe support and lasting mechanism, of a power-operated member for imparting to a shoe on said support heightwise movement relatively to the lasting mechanism, said member being mounted for preliminary movement by the operator to position it in relation to the shoe, and means operative in response to the preliminary movement of said member to start the power operation of the machine.
87. In a machine of the class described, the combination with a shoe support and lasting mechanism, of a presser member arranged to engage the bottom of a shoe on said support and movable manually to a position over the bottom of the shoe, power-operated means for thereafter moving said member heightwise of the shoe, and means controlled by the manual movement of said member for starting said power means in operation.
88. In a machine of the class described, the combination with a shoe support and lasting mechanism, of a shoe depressor movable manually to a position over the bottom of a shoe on said support, power-operated means including a clutch for imparting to said depressor movement to depress the shoe relatively to the lasting mechanism, and means for actuating said clutch by the manual movement of said depressor into position over the bottom of the shoe.
89. In a machine of the class described, the combination with a shoe support and lasting mechanism, of a toe presser foot and a heel presser foot movable by power to depress a shoe on said support relatively to the lasting mechanism, said toe presser foot being movable manually to a position over the bottom of the shoe, and means operative in response to the manual movement of said toe presser foot to start the power operation of the machine.
90. In a machine of the class described, the combination with a shoe support, power-operating means, and lasting mechanism mounted for preliminary positioning movement in relation to a shoe on said support, of means for preventing the starting of the power operation of the machine unless said lasting mechanism has received its positioning movement.
91. In a machine of the class described, the combination with a shoe support, power-operating means comprising a clutch, means for actuating said clutch, and lasting mechanism mounted for preliminary positioning movement in relation to a shoe on said support, of means controlled by said lasting mechanism for preventing operative movement of said clutch-actuating means until after the lasting mechanism has received its positioning movement.
92. In a machine of the class described, the combination with a shoe support, power-operating means, and lasting mechanism mounted for preliminary positioning movement in relation to a shoe on said support, of a member arranged to operate on the shoe and movable manually to position it in relation to the shoe, means for starting the power operation of the machine in response to the manual movement of said member, and means for preventing the movement of said member until after said lasting mechanism has received its positioning movement.
93. In a machine of the class described, the combination with a shoe support, power-operating means comprising a clutch, and lasting mechanism mounted for preliminary positioning movement in relation to a shoe on said support, of a presser foot movable manually to a position over the shoe, means for actuating the clutch in response to such movement of the presser foot, and means controlled by said lasting mechanism for preventing actuation of the clutch by movement of the presser foot until after the lasting mechanism has received its positioning movement.
94. In a machine of the class described, the combination with a shoe support, power-operating means comprising a clutch, and lasting mechanism mounted for preliminary positioning movement in relation to a shoe on said support, of a presser foot movable manually to a position over the shoe, means for actuating the clutch in response to such movement of the presser foot, a device for locking the presser foot to prevent its clutch-actuating movement, and means operative in response to the positioning movement of said lasting mechanism to cause said device to unlock the presser foot.
95. In a machine of the class described, the combination with a shoe support, means for operating on a shoe on said support, and means for removing the shoe after it has been

- operated upon, of a power-operated member through which movement away from the shoe is imparted to said operating means and through which operative movement also is imparted to the shoe-removing means, and automatic means for stopping the operation of said member if said operating means is accidentally so positioned as to interfere with the removal of the shoe.
96. In a machine of the class described, the combination with a shoe support, means for operating on a shoe on said support, and means for removing the shoe after it has been operated upon, of power-driven means comprising a clutch through which movement away from the shoe is imparted to said operating means and through which operative movement also is imparted to the shoe-removing means, and mechanism controlled by said operating means for actuating said clutch to stop the power operation of the machine if said operating means is accidentally so positioned as to interfere with the removal of the shoe.
97. In a machine of the class described, the combination with a shoe support, lasting mechanism, and means movable to a position previously occupied by a portion of the lasting mechanism to remove a shoe from the shoe support after the lasting operation, of a power-operated member through which movements are imparted both to the lasting mechanism and to the shoe-removing mechanism, and automatic means for stopping the operation of said member if the lasting mechanism is accidentally so positioned as to interfere with the shoe-removing mechanism.
98. In a machine of the class described, the combination with a shoe support, lasting mechanism movable away from a shoe on said support after operating thereon, and means movable to a position previously occupied by a portion of said lasting mechanism to remove the shoe after the lasting operation, of a power-operated member through which movement away from the shoe is imparted to the lasting mechanism and through which also operative movement is imparted to the shoe-removing mechanism, and automatic means for stopping the operation of said member if the lasting mechanism is accidentally in a position adjacent to the shoe at the time of the operation of the shoe-removing mechanism.
99. In a machine of the class described, the combination with a shoe support, lasting mechanism movable away from a shoe on said support after operating thereon, and means movable to a position previously occupied by a portion of said lasting mechanism to remove the shoe after the lasting operation, of power-driven means comprising a clutch through which movement away from the shoe is imparted to said lasting mechanism and through which also operative movement is imparted to the shoe-removing mechanism, and means controlled by said lasting mechanism for actuating said clutch to stop the power operation of the machine if the lasting mechanism is accidentally so positioned as to interfere with the shoe-removing mechanism.
100. In a machine of the class described, the combination with a shoe support, lasting mechanism, and means for removing a shoe from said support after the lasting operation, of power-operated mechanism including a latch for moving said lasting mechanism away from the shoe and for holding it away from the shoe to permit the removal of the shoe, a power-operated member for controlling said latch and for also operating the shoe-removing mechanism, and automatic means for stopping the operation of said member if the lasting mechanism is accidentally not held by said latch in a position away from the shoe at the time of operation of the shoe-removing mechanism.
101. In a machine of the class described, the combination with means for subjecting the opposite sides of an unlaced upper on a last between its forepart and its heel end portion to lasting strain tending to displace it heightwise of the last, of means movable into engagement with a portion of the upper thus subjected to lasting strain before the strain is applied to hold it against such displacement.
102. In a machine of the class described, the combination with means for subjecting the opposite sides of an unlaced upper on a last between its forepart and its heel end portion to lasting strain tending to displace it heightwise of the last, of devices movable into engagement with the upper at the opposite sides of the last in locations where the upper is thus subjected to lasting strain to clamp it against the last before the strain is applied and thus prevent its displacement, said devices being arranged to engage the upper at substantial distances from the bottom of the last to leave substantial portions of the upper at the sides of the last subject to the lasting strain.
- In testimony whereof I have signed my name to this specification.
- BERNHARDT JORGENSEN.
